KNITTING MACHINE

Max C. Miller, Cumberland, R. I., assignor to
 Knitting Machines Corporation, a corporation
 of Delaware

Application May 18, 1934, Serial No. 726,285

102 Claims. (Cl. 66—96)

The present invention relates to knitting machines, and is more particularly concerned with the provision of a novel and improved mechanism adapted for use with a flat full-fashioned, Cotton 5 type or similar machine for the forming of a setting-up course, and for thereafter returning it to the needles to produce a turn welt fabric.

It is a principal object of the present invention to provide novel and improved yarn handling instrumentalities which are particularly well adapted 10 for certain and efficient operation in a machine of this general description to receive the initial loops of the welt portion of the fabric, and thereafter to return these loops to the needles.

15 It is a further object of the invention to provide supporting and controlling mechanisms for the welt turning instrumentalities referred to, which may be applied as a separate unit to commercial machines, and substantially without change to 20 the existing mechanisms in these machines to secure an efficient cooperation of these instrumentalities with the needles and their cooperating knitting elements to turn the welt.

It is another object of the present invention to 25 further improve the construction and operation of the cooperating mechanisms for turning the welt to produce a machine which will be more fully automatic in operation than any heretofore produced and will operate substantially without 30 any attention from the operator.

It is a further object of the present invention to provide a new and improved method of co-ordinating the operation of a series of loop taking instrumentalities with the needles and their co-operating knitting elements to take a setting-up course of needle wale loops on said instrumentalities, and for thereafter drawing these loops to the backs of the needles during the subsequent knitting 35 of the fabric.

40 With these and other objects in view, as may hereinafter appear, a principal feature of the present invention consists in the provision in a flat full-fashioned knitting machine employing spring beard needles and sinkers to sink the yarn about 45 the needle shanks, of a series of instrumentalities arranged for movement relatively to the needles to engage with and lift from alternate needles kinks of yarn sunk about the needle shanks to 50 form a setting-up course of needle wale loops for the fabric. These instrumentalities operate during the knitting of subsequent courses to tension the fabric loops to the backs of the needles, and are further arranged upon the completion of the welt portion of the fabric for movement relatively to the needles to return the loops held

thereon to the needles. These instrumentalities comprise hook elements having their shank portions when in operative position arranged to extend substantially parallel to the needle shanks, and provided each with two hooks or cheeks which are adapted to extend to either side of the shank of the cooperating needle, and are provided with tapered tips which are bent inwardly around and to the rear of the needle shank. These instrumentalities are constructed and arranged to permit them to be moved downwardly between the press edge and the needles, in their high position, then to be forced or snapped into position with the cheeks extending as above described around and to the rear of the needle shanks, and thereafter to be lifted with relation to the needles to engage with and lift bights of yarn kinked thereon off the needles and clear of the needle beards. In order to facilitate the return of the loops to the needles, the hook instrumentalities referred 15 to, are provided on their under sides and between the cheek portions with guiding surfaces so that they may be placed over the rising needles to cause the needle tips to rise between the cheeks and through the loops held thereon.

With the construction and mode of operation of the hook instrumentalities herein described, it will be seen that these instrumentalities are located for both the loop taking and return operations between the sinkers and knock-over bits, 30 and also between the needles and the press edge, so that an absolutely accurate register of these elements with the needles is insured at all times to prevent any possibility of failure of the needles and instrumentalities from moving accurately and 35 surely into proper relationship.

The instrumentalities for taking and for returning the loops to the needles, are mounted on a swinging frame or hanger which is pivotally mounted on horizontal supporting lever arms which are in turn secured to a rock shaft, so that the hooks may move freely toward and away from the press edge with the pendulum-like movement of the frame, and may be moved vertically into and out of position with relation to the needles with the vertical movement of the supporting levers on their rock shaft above referred to. In order to insure an accurate register of the hooks between the sinkers and web holders, and to insure the proper cooperation of the hooks with the needles, the hooks are rigidly mounted on a bar or carriage which is supported on the frame to permit a limited lateral movement of the bar and hooks, and is accurately registered with relation to the machine as the frame and hooks are moved

into cooperating relationship to the knitting elements, by means of guide plates which are adapted to engage with corresponding surfaces fixed on the machine frame.

5 In order to impart the required movements to the hooks, both in a vertical direction and horizontally toward and away from the press, an additional cam shaft timed to rotate in unison with the main cam shaft, is mounted above the table 10 of the machine, and is provided along its length with operating cams for controlling the co-operating movements of the hanger or frame provided with each individual section.

15 The assembly of the hanger support for the hooks above described, and the auxiliary cam shaft mounted adjacent thereto, combines with a high degree of control and rigidity of the parts, the greatest possible mobility and ease of movement in the desired directions which it is believed possible to obtain. The hanger, free to swing with a pendulum-like movement from above, provides the least possible resistance to the rapid vibratory take-up movements required to follow the in and out movements of the needles, since the weight and frictional loss of a 20 pendulum mounting is reduced to an absolute minimum. The delicacy of the take-up action is further enhanced by the use of a relatively small sheave wheel to which is attached a strap and a heavy weight, so that relatively large 25 changes of weight will produce exceedingly delicate adjustments in the take-up tension. It is a noteworthy feature of the present construction that it is applicable as a unit to existing machines, and may be applied without altering or 30 replacing any of the existing parts, and with only the few additional parts necessary to enable the existing chain control of the machine to automatically cause the welt attachment to function 35 at the required times. Furthermore, the new mechanism is extremely simple and compact in construction, and is located on the machine to avoid any possible interference with the movements of the operator or with existing parts of 40 the machine.

45 Cam operated means controlled from the usual pattern chain of the machine, are provided for imparting lengthwise movement to the secondary cam shaft in opposite directions from an intermediate neutral position to set in operation appropriate cams for controlling both the vertical and swinging movements of the frame and hooks to take and to return the loops to the needles to complete the turning of the welt.

50 In order to insure the efficient and accurate operation of the several cooperating mechanisms to cause the hook instrumentalities to be moved into position between the press edge on the one hand and the needles and yarn kinked about the 55 shanks thereof on the other hand, and thereafter to engage and remove loops from alternate needles, certain changes and improvements in the operation of a full-fashioned machine of the type herein generally described, have been found 60 necessary. These changes involve a new mode of operation of the several cooperating elements, together with a number of mechanical improvements to insure the most efficient operation of the 65 cooperating parts.

70 One improvement contemplated in the mode 75 of operation of the machine consists in a movement of the yarn carrier from its usual stop position on the right to the left side of the machine to lay the yarn on the nibs of the sinkers and thus to remove the yarn carrier prior to the

operation of the slur-sock to advance the jack sinkers and sink yarn about the needle shanks. In this manner a sufficient amount of time is provided to permit the movement of the hook elements between the press edge on the one hand, and the needles and new yarn on the other hand at the completion of the slur-cock movement and before the needles have been moved downwardly to form the first course.

With this mode of operation it will be evident 10 that the kinked yarn must be held tightly about the needle shanks by the sinkers in order to prevent possible engagement of the yarn by the hooks during their downward movement, with resulting breakage or misplacing of the yarn. 15 In accordance with the present invention, novel and improved means are provided in the form of a jack sinker bar which is tripped into action at the end of the slur-cock movement across the section to engage with and hold all of the jack 20 sinkers yieldingly in their extreme forward position against the verge plate, so that the kinked yarn is held closely against the needle shanks and out of the path of the downwardly moving hooks.

25 In view of the extremely limited space available for the cooperative movements of the needles and hooks between the sinker and knock-over elements to take the initial needle wale loops which are to form the initial course of the 30 welt portion of the fabric from the needles, and in order to avoid possible interference of the needle beards with the sides of the hook instrumentalities during the relative downward movement of the needles and upward movement of 35 the hooks, mechanism is herein provided for varying the usual needle motion at this point to cause the needles to be moved an abnormal distance away from the press edge, so that the hooks are entirely disengaged or snapped off from 40 the needle shanks with the loops held thereon before they have reached the relatively thick eye portions of the needles. Inasmuch as the movement of the needles during this portion of the 45 knitting cycle is ordinarily controlled by means of a regular motion adjustable to determine the length of stitch, one feature of the present invention consists in the provision of mechanism for suspending the operation of this adjustment to permit a movement of the needles away from 50 the press after the completion of the yarn sinking operation a considerably greater distance than would otherwise be permitted by the contours of the cams to disengage the needles from the hooks.

55 In accordance with another feature of the present invention, mechanism is provided which is controlled from the pattern chain of the machine to place in active operation a welt wire which may be of ordinary description and is attached to a secondary take-up, so that the function of taking up the fabric is transferred after the knitting of a few initial courses from the hanger and welt hooks supported thereon, to the 60 welt wire and secondary take-up, which then operate during the continued knitting and subsequent return of the initial welt loops to the needles to draw the fabric beneath and to the rear of the hanger and hooks.

65 The several features of the present invention 70 consist also in the devices, combinations and arrangement of parts, and also in the steps of the method hereinafter described and claimed, which together with the advantages to be obtained thereby will be readily understood by one skilled 75

in the art from the following description taken in connection with the accompanying drawings, in which Fig. 1 is a cross section looking from the left, of a flat full-fashioned, Cotton type knitting machine, only so much of the machine having been illustrated as is necessary to show the connection of the present invention therewith; Fig. 2 is a fragmentary sectional view of the chain control mechanism; Fig. 3 is a front elevation of the upper portion of the left hand end of the machine showing two of the knitting sections; Fig. 4 is an end view cross section taken on line 4—4 of Fig. 3; Fig. 5 is a fragmentary end view showing the welt hook bar swung upwardly to inactive position; Fig. 6 is a fragmentary end view illustrating in detail one of the cam rollers and its mounting; Fig. 7 is a plan view of the jack sinker bar control mechanism taken on line 7—7 of Fig. 4; Fig. 8 is a rear elevation illustrating particularly the turn welt and jack sinker bar mechanism extending over two sections; Fig. 9 is a broken large scale front elevation of the welt hook bar and support; Fig. 10 is an end view of the parts shown in Fig. 9; Fig. 11 is a fragmentary plan view of parts shown in Figs. 9 and 10; Fig. 12 is a front elevation showing the loose course and welt turning mechanism chain control; Fig. 13 is a fragmentary plan view of the jack sinker bar shown in Fig. 4; Fig. 14 shows the cams used to give the hook bar of the turn welt mechanism its in and out and idling movements; Fig. 15 shows the cams used to give the hook bar of the turn welt mechanism its up and down movements; Figs. 16 to 34 inclusive are fragmentary end views showing the position of the knitting elements and the welt hooks during the various stages of setting up and during subsequent welt fabric knitting, in which Fig. 16 shows the welt hooks going into position prior to their engagement with the needles just prior to the set-up; Fig. 17 shows the welt hooks as having engaged with the needles prior to engaging with the initial yarn of the setting-up course; Fig. 18 shows the welt hooks engaging with yarn of the setting-up course; Fig. 19 shows the welt hooks engaging with the yarn of the setting-up course prior to the dividers moving into their forward position; Fig. 20 shows the welt hooks engaging with the setting-up course, with the dividers in their forward position and the needles as having moved downwardly and away from the hooks; Fig. 21 shows the welt hooks engaged with the yarn of the welt course, with the needles moved downwardly and toward the hooks; Fig. 22 shows the hooks engaged with the yarn of the initial welt course, with the needles moved downwardly; Fig. 23 shows the hooks engaged with the yarn of the initial welt course, with the needles moved downwardly and the hooks upwardly; Fig. 24 shows the hooks engaged with the initial welt course, with the needles moved downwardly to the press position; Fig. 25 shows the hooks engaged with the initial welt course, with the needles moved downwardly and slightly away from the press; Fig. 26 shows the hooks engaged with the initial welt course, with the needles and hooks moved downwardly away from the press edge of the machine; Fig. 27 is a continuation of the movements noted in Fig. 26; Fig. 28 is a continuation of the movement shown in Figs. 26 and 27, with the needles in position just prior to their return movement in a direction toward the press; Fig. 29 shows the needles as having moved toward the press edge of the machine with the welt hooks engaged with the initial welt or setting-up

course; Fig. 30 shows the needles having moved still further toward the press edge, with the welt hooks engaged with the setting-up course and standing at the back of the needles, somewhat lower than in Fig. 29; Fig. 31 shows the needles moving upwardly, getting into position for the second course, with the welt hooks engaged with the setting-up course, the hooks standing at the back of the needles, with the setting-up course held down by the sinker noses; Fig. 32 shows the needles fully raised, ready to have the second course of yarn kinked around them, with the welt hooks still engaged with the setting-up course and standing at the back of the needles; Fig. 33 shows the relationship of the elements, after a part of the welt has been knitted, with the welt hooks having taken up the fabric as it was produced by moving away from the needles; and Fig. 34 shows the elements with more welt fabric knitted, with the hooks in a fixed intermediate position and with the welt rod which has been automatically inserted, now acting as the fabric take-up means; Figs. 35 to 46 inclusive are fragmentary end views showing the position of the knitting elements and the welt hooks during the various stages of transferring the setting-up course back to the needles, in which Fig. 35 shows the welt hooks moving toward the needles and being lifted clear of the underlying welt fabric and selvages, during which movement the sinkers are moving toward the needles to kink yarn for the course preceding the transfer; Fig. 36 shows the course of yarn, preceding the transfer, on the nose of the sinkers, with the welt hooks moving toward the needles; Fig. 37 shows the course prior to the transfer just before it is formed into loops by the downward movement of the needles, with the welt hooks moved still further toward the needles; Fig. 38 shows the course of yarn, prior to the transfer, as having been formed into loops, by the knockover bits, after the welt hooks have passed the needles in the movement of the hooks toward the press edge of the machine; Fig. 39 shows the needles and the welt hooks moving toward the press edge of the machine, with the hooks ahead of the needles; Fig. 40 shows the welt hooks as they reached and contacted with the press edge of the machine, with the needles continuing to move in that direction; Fig. 41 shows the needles at their farthest movement toward the press edge and the welt hooks resting against the press edge, with the hooks of the needles engaging with the welt hooks; Fig. 42 shows the hooks still against the press edge, but slightly lower than in Fig. 41, with the needles raised, having therefore passed through the setting-up course held by the welt hooks; Fig. 43 shows the hooks still against the press edge, but in a lower position, so that the setting-up loops with which they were engaged are cast off the hooks onto the needles; Fig. 44 shows the needles moved upward and away from the press, with the hooks in position after they have commenced their upward motion; Fig. 45 shows the needles as having continued to move upwardly and away from the press, with the welt hooks also moved upwardly; and Fig. 46 shows the needles at the end of their upward movement, with the welt hooks in various stages of being lifted over the needles and with the sinkers fully retracted prior to the laying of the yarn for the next course; Figs. 47 to 54 inclusive are enlarged fragmentary plans, in partial-course section, showing the sinkers, needles and welt hooks in their various positions during the setting-up and transfer, in which Fig. 47 shows the initial welt 75

or setting-up yarn engaged by the jack sinkers, with the hooks in about the position shown in Fig. 16; Fig. 48 shows the welt hooks engaged at alternate needles with the setting-up yarn about as shown in Fig. 18; Fig. 49 shows the welt hooks engaged with the setting-up course prior to the movement of the dividers between the needles, the elements including the welt hooks being about as shown in Fig. 19; Fig. 50 shows the hooks engaged with the setting-up course and the dividers fully projected, with the elements including the welt hooks about as shown in Fig. 21; Fig. 51 shows the welt hooks engaged with the setting-up course, the dividers fully projected, with alternate needles flexed against the setting-up yarn, all the elements being about as shown in Fig. 21; Fig. 52 shows the elements in about the position shown in Fig. 23, with every other needle about to cast off the setting-up yarn; Fig. 53 shows the elements about in the position shown in Fig. 24, after every other needle has cast off its yarn and with alternate needles engaged with the setting-up yarn; Fig. 54 shows the hooks at the back of the needles with the setting-up yarn in the hooks and around alternate needles, the elements being in about the position shown in Fig. 32; Fig. 55 is an enlarged partial front elevation, showing the elements in about the position shown in Fig. 29, with the setting-up yarn in the welt hooks and in the hooks of alternate needles; Fig. 56 is an enlarged plan view of the fabric as it would appear after the third course of the welt fabric has been knitted, showing the welt hooks and the needle shanks in cross section; Fig. 57 is a fragmentary front elevation showing the needles, hooks and sinkers and set-up yarn in a position relative to each other about as shown in Fig. 3; Fig. 58 is an enlarged fragmentary sectional plan showing the transfer of the loops held on the hooks back to the needles, and corresponds substantially to Fig. 43; Fig. 59 shows an enlarged perspective view of the welt hooks; Fig. 60 is an end view cross section of the stitch regulator and loose course cam taken on line 60—60 of Fig. 12; and Fig. 61 is a detail sectional view taken on the line 61—61 of Fig. 12.

The machine disclosed in the drawings as embodying in a preferred form the several features of the present invention, comprises a flat full-fashioned knitting machine of the Cotton type having a number of sections, each of which comprises a series of spring beard needles which are given vertical reciprocatory movements to pull down the loops, and lateral movements toward and away from a fixed pressing surface to close the needle beard and cast off the old loops, together with the usual cooperating sinkers and knockover bits common to this type of machine. The machine is provided along its length with frames 100 as best illustrated in Figs. 1 and 12, a frame of this type being provided between each two sections of the machine. These frames support bearings for the several driving and control shafts extending for the most part throughout the length of the machine, including specifically the main drive shaft, 102, the hand wheel shaft 104, the knockover bit shaft 106, the presser shaft 108, the needle bar shaft 110, the front catch bar and jack spring shaft 112, the back catch bar shaft 114, and the back narrowing shaft 116, and also have secured thereto the back rail 118, the sinker rail 120, the front rail 122, and the table 124. The cam shaft 102 is rotated in the direction of the arrow Fig. 1, there being rigidly fastened thereto the cams for causing the various roller levers with which the cams are associated, to move the differ-

ent parts of the machine. On the table 124 which extends throughout the machine length, there are fastened at intervals the upwardly extending secondary cam shaft brackets 126 (Figs. 3 and 4), one between each two sections. As shown in the drawings, and more particularly in Fig. 3, there is fastened to the table 124 at the left hand end of the machine, a somewhat similar bracket 128 to which is fastened an end bracket 130 for supporting the left hand end of the secondary cam shaft. In the brackets 126 and 130 there is supported, free to rotate and free to move endwise, the secondary cam shaft 132 which rotates in the direction of the arrow, Fig. 1, in unison with the regular cam shaft 102, a chain or other suitable form of connecting drive being used, as for instance the sprocket chain 103 indicated in dot-and-dash lines in Fig. 4 passing over similar sprockets mounted on the shafts 102 and 132 respectively.

The secondary cam shaft 132 has rigidly fastened to it at the left hand end of the machine, a shift cam disk 134 for shifting the cam shaft to the right, as when going into the set-up, and a shift cam disk 136 for shifting the cam shaft to the left, as when about to transfer the setting-up course back to the needles.

The bracket 128 supports a cam shaft shift lever 138 rigidly fastened to a pin 140 which is free to turn in the bracket 128. Supported in the upper end of the shift lever 138 is the roller 142 rotating freely on a pin 144. A locking-out roller 146 mounted free to rotate on a pin 148 fixedly fastened to the shift lever 138, permits the cam 150, adjustably fastened to the shift cam 134, to move the shift lever and its roller 142 outward, so that the neutralizing cams 152 and 154 can shift the cam shaft 132 to a position central between its right and left positions.

Fastened rigidly to the right hand end of the pin 140 is a shift lock lever 156 (Fig. 1). A shift latch 158 contacts with the surface 160 of this lever 156, thereby holding the shift lever 138 in its outward or neutralized position, the latch 158 being mounted free to fulcrum on the fixedly positioned pin 162. A spring 164 holds the acting end of the latch 158 down against a stop 166. The other end of the latch 158 is connected by means of a link 168 with one arm of a pattern chain actuated lever 170, see Fig. 12. The chain lever 170 is free to turn on a pivot 172 mounted in a bracket 174 rigidly fastened to the front rail 122 of the machine. An upwardly extending arm of the chain lever 170 has an end 176 so that suitably positioned and differing height chain bumps 178 can pull the link 168 downwardly and so can raise the end of the latch 158 (Fig. 1) where it contacts with the lever 156 in one of two positions, a low bump causing it to contact with the surface 180, and a high bump causing it to contact with the surface 182 on the lever 156. A tension spring 184 positions the lever 156 as may be dictated by the movement of the latch 158. When the latch 158 is raised, the spring 184 causes the shift lock lever 156 to contact the latch with its 180 surface, the cam shaft shift lever 138 with its roller 142 thereby moving in a direction toward the cam shaft 132, so that its roller will be placed in line with the shift cam 186 (Figs. 1 and 3) and upon continued rotation of the machine and the cam shaft 132, the cam shaft will be shifted to the right and its cams shifted so that they will cause the pendulum and the welt hooks to operate during the set-up. The raising of the latch 158 and subsequent move-

ment of the roller 142 is such as to permit the roller 142 to fall into position at the open space between the various cams on shift cam disks 134 and 136. The cam shaft now shifted to the right, on continued rotation of the machine will remain in this shifted position until the open space between the cams again comes opposite roller 142, that is, when somewhat less than one revolution has been made, at which time cam 150 contacts with the locking-out roller 146 and upon continued rotation of the machine, positions the shift roller 142 outwardly so that it is in line with the neutralizing cam 154 and upon continued rotation the cam shaft 132 will be shifted to the left, or into its neutral position. During this partial revolution, the chain bump 178 has come out from under the portion 176 of the lever 170 (Fig. 12) and so permits the latch 158, as the shift lock lever 156 is moved away from the latch, to fall downwardly due to the action of its spring 164, and thereby again contact with the surface 160 of the lever 156, in this manner locking the shift mechanism into a position where the neutralizing cams 152 and 154 can hold the cam shaft 132 in its neutral or idle position. When it is desired to shift the cam shaft to the left, as is necessary prior to the transfer, a high chain bump is racked into position under the end 176 of the lever 170 (Fig. 12), thereby moving the link 168 downwardly, permitting the shift lock lever 156, due to the action of the tension spring 184, to move toward the latch 158 and contact with its surface 182, thereby moving the roller 142 in a direction toward the cam shaft 132 the proper distance to cause the shift cam 188 to be aligned with it, so that upon continued rotation of the cam shaft, the cam 188 will contact with the roller 142 (Figs. 1 and 3) and shift the cam shaft 132 to the left, or into its transfer position, in which position it will remain for somewhat less than one revolution or until the locking-out cam 150 contacts with the roller 146 which causes the shift lever 138 with its roller 142 to be moved in a direction away from the cam shaft 132 so that the roller is again aligned with the neutralizing cam 152. Upon continued rotation of the machine this cam will contact with the roller 142, thereby shifting the cam shaft into its neutral position and as the high chain bump has, in the interim, moved out from under the chain lever 170, the latch 158 is drawn downwardly by the action of its spring 164 into a position where it can again engage with the surface 160 of the lock lever 156, and so lock the shift lever into its neutral position.

Between each pair of brackets 126 and at the left hand end of the machine between the two brackets 126 and 128, a shaft 190 is supported, free to rotate in the brackets. There is a shaft of this kind for every two sections of the machine, that is, the shaft does not extend in one piece throughout the machine length, in order that excessive expansion and contraction as would occur in a long shaft, may not interfere with the pendulum lateral adjustment. Rigidly fastened to this shaft are three horizontal supporting lever arms 192 in which there is rigidly fastened a hanger pivot shaft 194, one for each two sections of the machine. Mounted to freely oscillate on the shaft 194 is a swinging frame or hanger 196, one for each section, a sleeve connecting the two outer hubs of the frame into a rigid unit. Forming a rigid part of this sleeve is a sheave wheel 198, one for each section, to which is fastened a counterweight tape 200 wound

or more turns around the sheave wheel 198. This tape 200 is supported at the back of the machine (Fig. 4) by an idler 202 and hangs from this idler at the back of the machine, the lower end being connected to a series of counterweights 204. The 5 tape idlers are supported free to rotate on a rod 206 which is carried by extensions from the brackets 126 and 130 and extends throughout the length of the machine.

The resultant action of the counterweight, as 10 clearly shown in Fig. 4, will be to move the swinging frame or hanger toward the right or front of the machine. In order that the counterweights do not normally move the hangers further forward than desired, each of the brackets 126 and 15 130 rigidly supports a pin 208 to which is fulcrumed for free movement a hanger latch 210 (Fig. 4), the hook end of which engages with an extension 212 (Fig. 3) of the hanger 196.

The angular position of the shaft 190 and the 20 hanger supporting arms 192 secured thereto for determining the vertical position of the welt hooks, is determined by means of one or more identical cam levers 214 which are secured to the shaft 190 preferably one about midway between every two sections. Each lever 214 is fitted at its outer end near the cam shaft 132 with a rigid pin, the ends of which extend outside of both ends of the lever 214 to support rollers 216 and 217 (Fig. 3) which are arranged 30 upon endwise movement of the cam shaft 132 to cooperate respectively with two normally inoperative cams 218 and 219 integrally formed with a cam hub 226 rigidly secured to the cam shaft 132. The lever 214 is also fitted with an adjustable 35 roller post 220 (Fig. 4) carrying a rigid pin which supports a freely rotatable roller 222. This roller rides on a circular disk 224 also formed on the cam hub 226. Forming a rigid part of the lever 214 is an extension 228 (Fig. 4) to which is fastened a tension spring 230, the other end of which is fastened to a rod 232 extending throughout the machine length and supported in extensions of the brackets 126 and 130.

The assembly just described, therefore, supports the three horizontal supporting levers 192, the shaft 194 and two hangers 196, the spring 230 holding the lever 214 with its roller 222 tightly against the disk 224. The rollers 216 and 217 are provided so that when the cam shaft 50 132 is shifted to the right or left, the cams 218 or 219 respectively supported by the hub 226 will cause the frame assembly to move up and down.

The several swinging frames or hangers 196 are moved positively toward and away from the 55 press during the operations of taking and of returning the loops to the needles through cam actuated connections from the auxiliary cam shaft 132, a separate actuating mechanism being provided for the actuation of each frame. This 60 mechanism comprises a lever 234 for each section, mounted to swing freely on the shaft 190, and provided at its free end with two follower rolls 236 and 237 which are mounted on eccentric pivot pins for adjustment with relation to their 65 operating cams indicated respectively at 238 and 239 on a sleeve 248 secured to the cam shaft 132. The lever 234 also has mounted thereon an adjustable roller post 240 (Fig. 6) which carries a roller 244 adapted to ride on a circular disk 246 70 forming a rigid part of the cam hub 248. There is secured to the hub of the lever 234 a depending arm 250 (see Figs. 3 and 4) which is connected by means of a bolt 252 to a similarly downwardly extending lever arm 254 which is thus adjustably 75

secured to turn as a unit with the cam lever 234. There is also secured to the hub of the lever 234, an upwardly extending arm 256 to which is secured a tension spring 258 which acts to hold the lever and follower rolls mounted thereon in engagement with the cams on the cam shaft 132. The downwardly extending lever arm 254 has mounted thereon a latch lever or link 260 which has at its other end a recess 262 adapted for engagement with a pin 264 mounted on a bracket 266 on the hanging frame 196. There is also formed on the latch lever arm or link 260, a curved upwardly extending arm 268 which is provided at its tip with a pin 270 and is adapted 10 normally to ride on a circular disk 272 on the cam shaft 132. A spring 274 holds the latch lever arm or link 260 down so that the arm 268 rides tightly against the disk 272. The connection 15 between the latch lever arm 260 and depending lever 254 consists preferably of an eccentric pivot pin 276 which may be turned to secure an adjustment in the position of the latch lever 260 with relation to the lever arm 254. With this construction and arrangement of the parts, 20 it will be seen that with the secondary cam shaft 132 in the neutral intermediate position illustrated in Fig. 3, the engagement of the curved arm 268 with the disk 272 acts to hold the latch lever in a raised inoperative position. When the cam shaft 132 is shifted either to the right or to the left, the disk 272 rides out from under the arm 268, permitting the latch lever 260 and recess 262 to drop into engagement with the pin 264 on the hanging frame 196 to lock these parts 25 into operating engagement, so that the movements of the hanging frame 196 toward and away from the press will now be positively controlled by the movement of the cam actuated lever 234. At the end of a complete revolution of the cam shaft 132, the latch lever 260 is again raised to its inoperative position to permit the movement of the disk 272 under the curved arm 268 as the cam shaft 132 is again returned to its neutral position, by the engagement of the pin 270 with a 30 cam portion of the disk 272 or with a cam disk 278 depending upon the operating position of the cam shaft 132.

At the lower end of each swinging frame or hanger 196, is supported a welt bar 282 to which 35 are rigidly secured a series of welt hooks 283, one being provided to cooperate with each alternate needle. The welt bar 282 is mounted to move freely with relation to the supporting hanger within predetermined limits lengthwise of the 40 needle series, so that the hooks of each section may be readily registered in their proper positions with relation to the needles. For this purpose two guide plates 284 are mounted one at each end of the welt bar 282 to engage with corresponding abutments formed on fixed portions of the machine as the hooks are moved into operative position to guide the hooks accurately into register with the needles. The welt bar is mounted 45 also to permit the hooks to move yieldingly downward with relation to the hanger particularly to secure a predetermined uniform tensioning strain on the initially formed loops on the hooks as the needles move to their extreme low or knockover position, irrespective of any slight 50 errors in the adjustment of the parts or in the length of the yarn kinks measured by the sinkers in the formation of the loose setting-up course.

As illustrated particularly in Figs. 3, 4, 9, 10 and 11 of the drawings, the lower end of each 55 hanger is formed with a split hub 285 in which is

rigidly secured a supporting shaft or pin 286. Adjacent the sides of the hub 285 on the shaft 286 are mounted two identical bell-crank levers 287 which are adjustably secured in a predetermined angular position with relation to the hanger 196 by means of clamping bolts 288 which are screw-threaded in the hanger 196 and project through over sized holes in the upper ends of the levers. There are also mounted on the shaft 286 adjacent each end thereof two lever arms 289 which together with a tie rod 290 formed integrally therewith provide a welt hook bar support which is freely movable about the shaft 286 as a pivot. The end portions of the shaft 286 which provide a bearing for the arms of the welt bar support 10 are formed eccentrically of the axis of the shaft, so that an adjustment of the position of the welt bar relatively to the hanger 196 may be readily obtained by merely varying the angular position of the shaft 286 in the hub 285. 15

The welt bar is mounted for a limited sliding movement with relation to the support 289 by means of two brackets 292 which are provided at each end of the tie rod 290 and have formed therein T-shaped guideways to engage with correspondingly shaped portions of the welt bar. Stop pins 294 mounted on the welt bar 282 beyond the ends of the guideways serve to limit the travel of the welt bar in either direction on its support. 20

The angular position normally maintained by the welt bar 282 and its supporting frame with relation to the hanger 196 is determined by the angular position of the bell-crank levers 287 above referred to, which are provided with horizontally extending arms arranged to engage with two positioning pins 295 formed on the inner sides of the lever arms 289, as best shown in Figs. 10 and 11. Tension springs 296 stretched between pins 297 on the hanger 196 and pins 298 on the arms 289 of the supporting frame tend normally to hold the parts in the operative position shown in Fig. 10. When so desired, the assembly of the supporting frame 289 and welt bar 282 can be swung in a counterclockwise direction to 45 the inoperative position shown in Fig. 5 for maintenance or for other reasons, where it is held by the springs 296, the lever arms 289 at this time being brought into engagement with two stop pins 299 formed on the back sides of the bell-crank levers 287. 50

The hook bar 282 is slotted, one slot being provided for each pair of needle slots, to form a support for the welt hooks 283, a number of short covers 300 and clamp bolts 301 holding the 55 hooks in the slots of the bar 282 as best shown in Fig. 11.

The guide plates 284 located at each end of the welt hook bar 282 for accurately registering the welt hooks with relation to the needles and other cooperating knitting elements, are constructed and arranged to provide engaging contacts with fixed portions of the machine frame to register the hooks with relation to the knitting elements at several different points in the operations of taking and of transferring the loops back to the needles. Each plate 284 is provided with a downwardly extending arm or end 302 which engages with a bevel designated at 303 on the press edge of the machine to insure that the hooks on 70 their downward movement between the press edge and the needles to take the initial course of loops, will not be caught against the press edge and damaged. During the further downward movement of the hanger 196 and welt bar 282, 75

the bevelled surfaces 304 below parts 310 of the plates 284 will engage with two adjustable stationary screws 314 to locate and centralize the welt bar 282 and hooks supported thereon with relation to the needles lengthwise of the needle series. During the operation of transferring the loops back to the needles when the welt hooks are moved laterally toward the press at a relatively low level, two additional bevelled surfaces designated at 306 on the plates 284 are brought into contact with the positioning screws 314 to locate the welt hooks particularly with relation to sinkers and knockover bits.

It will be noted that each of the guide plates 284 has formed on its outer or contact surface, a cut-away portion 310 which is adapted to provide substantially .002 or .003 inch clearance between the plates and the guide screws 314 for a position of the welt bar after the hooks have been registered with and have passed between the sinkers. This clearance enables the hooks after they have been guided between the sinkers to adjust themselves automatically for a maximum freedom of movement between the sinkers and web holders regardless of any slight changes in the positions of the cooperating elements which may be due to contraction or expansion of the metal, or to other causes.

The instrumentalities or hooks 283 for engaging the initial course of loops at the set-up, and for returning these loops to the needles after the knitting of the welt fabric, as previously mentioned, comprise vertically arranged bifurcated hooks which are arranged to move downwardly between the press edge and the needles at the completion of the kinking of the yarn by the jack sinkers to engage and take needle wale kinks of yarn from alternate needles, and thereafter during subsequent knitting to carry them to the backs of the needles. At the end of the welt turning operation the hooks are moved laterally toward the press and again between the sinkers and knockover bits to cause the loops during the subsequent rising movement of the needles to be returned thereto.

Fig. 59 of the drawings illustrates a preferred form of applicant's hook 283, which, as clearly shown comprises a rectangular shank of uniform width throughout its length to fit closely between adjacent sinkers, and provided at its lower end with two hook-shaped cheeks 307 which are arranged to embrace the needle shank between them, and are provided with pointed tips which are bent inwardly so that they will fit tightly around and to the rear of the needle shank. The bottom end of the implement is drawn out into a point formed by four bevelled surfaces which are arranged to facilitate an accurate register of the hook implements with relation to the correspondingly bevelled press edge and with relation to the two adjacent sinkers and knockover bits during the movements of the hooks with relation thereto. At the base of the slot formed between the two cheek members 307 there is provided a sloping cam surface 308 which extends from the pointed bottom extremity of the implement to the middle of the throat formed by the junction of the cheeks 307 with the shank of the implement. A long notch 309 is cut in the upper portion of the hook shank to engage with a corresponding ledge on the welt hook bar 282 to lock the hooks rigidly in position in the bar.

The present machine is provided with the usual jack and dividing sinkers, one jack沉器 being provided for every two needles with the dividing

sinkers alternating between them. As illustrated in Fig. 4, the dividing sinkers are indicated at 322, the jack sinkers at 324, the bottom and top sinker beds for supporting and guiding the sinkers being indicated at 326 and 328, the usual verge plate for preventing vertical drive of the sinkers at 330, the sinker jacks at 332, and the slur cock at 334. The slur cock is mounted for movement on the slur cock bar 336. A new feature of the present invention consists in the provision of means for holding the jack sinkers against the verge plate after they have kinked their yarn and prior to the advance of the dividing sinkers, in order to prevent any possibility of the welt hooks 283 displacing or breaking the yarn. This mechanism as illustrated particularly in Figs. 1, 4, 7, and 8, consists of a bar 338 (see particularly Figs. 7 and 13) which is pivotally connected to a U-shaped lever 340 by means of a pin 342, so that the bar may swing freely to level the sinkers evenly in their advanced positions against the verge plate. Two pins 344 are rigidly secured to the bar 338, and protrude upwardly through clearance holes formed in the lever 340 to limit the amount of the swinging movement permitted to the bar relatively to the lever 340.

The U-shaped lever 340 is mounted to turn on a pivot pin 346 carried on the upper end of a vertical lever arm 348 which is mounted to turn freely on the back catch bar shaft 114 of the machine. Secured to the hub of the U-shaped lever 340 is a downwardly extending arm 350 which has secured thereto a tension spring 352 to maintain the U-shaped lever 340 and sinker bar 338 firmly in engagement with the top sinker plate 328. A laterally extending arm 354 formed integrally with the lever 348, has secured thereto a tension spring 356 which tends to move the lever 348 about its pivot to advance the U-shaped lever 340 and jack bar 338 into engagement with the jack sinkers. The jack bar 338 is normally held in retracted position against the pressure of the spring 356 by means of a latch 358 which engages with a corresponding abutment 360 on the sinker bar 338.

This latch 358 is adjustably fastened to an extension of a hub 362 which is mounted free to oscillate on the back narrowing machine shaft 116, the hub 362 having formed thereon a hook 364 to which is fastened the spring 366 which is at its lower end connected to a spring hook collar 368, said collar also centralizing the lever 348 in conjunction with a collar 370. The spring 366 therefore holds the latch 358 in engagement with the tooth 360, the hub 362 having a long upwardly extending end 372 which at times is caused to engage with a pin 374 extending from the side of one of the welt cams so that when this pin 374 (Fig. 8) contacts with the end of the extension 372, the latch 358 will be lifted against the tension of the spring 366, thereby permitting the U-shaped lever 340 and its assembly of parts, including the bar 338, to move in a direction toward the verge plate 330 through the action of the spring 356, the movement of the bar 338 being timed to take place immediately after the last jack 332 has deposited its sinker against the verge plate at the end of the yarn laying stroke, so that the spring 356 can effectively hold the jack sinkers solidly against the verge plate 330. The pivotal mounting for the bar 338, as shown in Fig. 13, ensures that the bar will automatically level itself with relation to the verge plate 330 and jack and sinker elements engaging 75

therewith to ensure the proper positioning of all of these elements. Subsequently the operation of the catch bar 376 (Fig. 1) to engage with and withdraw the sinkers will cause the bar 338 to be retracted against the pressure of its spring 356 to its inoperative position where it is held by the engagement of the latch 358 with the abutment 360.

The present machine is provided with the usual 10 stitch adjusting or regulator mechanism which comprises a rock shaft 386 extending substantially the full length of the machine and having mounted thereon a number of identical levers 379 adapted to engage with the downwardly extending tips of the usual cam levers 381 for imparting the in and out movements to the needles toward and away from the press. The rock shaft 386 is turned on its axis to engage the levers 379 with the needle actuating levers 381 to locate the needle shanks laterally with relation to the press edge during the yarn sinking operation to measure the length of stitch by means of stitch regulator cam 400 on the main cam shaft 102 and connections actuated thereby 25 which include a cam lever 402 loosely pivoted on the rock shaft 386 and provided with a cam roll 398 adapted to ride on the periphery of the cam 400. A tension spring 383 is secured to the lever 402 to maintain the roll 398 at all times in engagement with the cam 400. Secured to the rock shaft 386 adjacent the lever 402 is an actuating lever 406 which carries an adjustable contact pin 404 adapted for engagement with the cam lever 402 so that as the lever 402 and roll 398 ride on the high portion of the cam 400, the resulting movement of the lever 406 and rock shaft 386 in a clockwise direction as shown in Fig. 60, will cause the position of the needles to be adjusted as above described. A spring 385 secured to a hook 387 rigidly mounted on the rock shaft 386 tends to rotate the shaft 386 in a counterclockwise direction to maintain the levers in engagement with their cams. The position of the needle shanks during the yarn sinking period may be readily adjusted to secure the required length of stitch by a simple adjustment of the contact screw 404.

There is also provided with the present construction mechanism which is controlled automatically from the pattern chain of the machine for moving the needles relatively close to the press edge during the setting-up operation to knit an initial loose course of welt fabric. This mechanism takes the form of a loose course cam 378 (see Fig. 12) rigidly secured to the main cam shaft 102 which is engaged during the setting-up operation by means of a cam roll 380 which is slidably mounted on a pin secured to a loose course actuating lever 388 mounted on the rock shaft 386. A lever 388 pivoted at 389 on the machine frame is operatively connected to control the movements of the roll into and out of the path of the loose stitch cam 378. A spring 391 attached to the lever 388 tends to hold the lever 65 and cam follower roll 380 normally in an inoperative position. For moving the lever 388 and roll 380 to the right as shown in Fig. 12 into operative position, a lever 392 is pivotally mounted on the front rail 122 of the machine, and is adapted 70 to its upper end to engage with a pin 390 on the lever 388. The lower end of the lever 392 is connected by means of a long link 394 to a pattern chain actuated lever 396 which is loosely pivoted to turn on the pivot pin 172. A spring 191 secured to the lower end of the lever 392 tends to

hold the lever 392 in a retracted position, and the pattern lever 396 in close proximity to the pattern chain.

With the present construction it has been found essential for the proper operation of the hooks to take the initial setting-up needle wale kinks from alternate needles, that a loose course must be employed. Any failure of the loose course mechanism to operate at this time must inevitably result in the jamming and possible serious injury to the machine. Another feature of the present invention is therefore directed to the provision of means for insuring the operation of the loose course mechanism during the operation of setting-up and placing the initial loops of the welt portion of the fabric on the hooks 283. To this end a single pattern chain bump is employed which will automatically and at the same time set in operation both the mechanism for advancing the hooks to take the initial loops of the welt fabric and the mechanism for moving the needles toward the press to make a loose course. The chain bump employed is somewhat like that shown at 170, is of the proper height to move the lever 170 and latch lever 158 only a single step 2 to the setting-up position previously described, but is wide enough to contact with and move the levers 170 and 396 simultaneously to operate their respective mechanisms.

In the operation of the loop taking instruments or hooks herein disclosed to take the initial course of loops, it has been found desirable after the hooks have engaged with the yarn kinks on the needle shanks and during the relative upward movement of the hooks to disengage the hooks from the needles in order to avoid catching the needle beards on the hooks and also to avoid having the thick eye portions of the needles pass between the hooks with possible jamming or interference of the parts. To this end one feature of the present invention consists in the provision of mechanism which is rendered operative immediately following the yarn sinking operation to move the needles away from the press an abnormal distance to disengage the needle shanks from the hooks. This mechanism consists in the provision of an adjustment in the regulator mechanism which is rendered operative during the setting-up operation to permit the required abnormal movement of the needles away from the press.

It will readily be seen from an inspection of Fig. 60 of the drawings, that the position of the regulator shaft 386 to determine the position of the needles during the setup, is controlled by 55 both the regulator cam 400 and the loose stitch cam 378 above described, the engagement of the roll 380 with the cam 378 giving the rock shaft 386 an abnormal movement in a clockwise direction during the yarn sinking portion of the knitting cycle. At this time the adjusting screw 404 will have been retracted out of operating relationship to the cam lever 402. In order to permit the needles to fall away from the sinkers shortly after the laying and kinking of the initial 60 loose course of yarn, the loose course cam 378 is cut away sharply as indicated at 408 in Fig. 60 to enable the loose course roller 380 to give the necessary motion to the regulator shaft 386 by falling inwardly toward the cam shaft 102. The 65 corresponding portion of the regulator cam 400 which performs a function during the normal knitting on the machine, however, cannot be cut away at this point. For a more complete description of the construction and mode of operation 70

of the regulator motion, reference may be had to the patent to Zwicky No. 1,417,289. In order to permit an abnormal movement of the regulator shaft 386 in a counter-clockwise direction to move the needles an abnormal distance away from the press, an adjustable connection is provided in the regulator mechanism which comprises a lever 414 which is mounted on the pivot 389 and has one end normally interposed between the regulator lever 402 and the end of the regulator screw 404. The lever 414 is also provided with an upwardly extending arm which engages behind the lever 388, being normally held in engagement therewith by a small tension spring 420. When the loose course lever 388 is moved to the right upon starting the machine, by operation of the pattern lever 396, link 394 and lever 392, the lever 414 will tend to swing about its pivot under the pressure of its spring 420, but will be held for the moment in its normal position between the lever 402 and pin 404 by the frictional engagement of these elements. However, as the roller 380 rides onto the high portion of its cam 378 to rock the regulator shaft 386 and lever 406 away from the lever 402, the lever 414 is permitted to move from between the pin 404 and lever 402 under the pressure of its spring 420, so that as the loose stitch cam roller 380 rides inwardly on the surface 408 immediately following the yarn sinking operation, the shaft 386 and lever 406 will be permitted to rotate a correspondingly great distance in a counter-clockwise direction as shown in Fig. 60. The end of the lever 414 is subsequently again permitted to drop into position between the pin 404 and the lever 402 of the regulator mechanism as the loose stitch cam roller 380 is again moved to the left under the pressure of its spring 391 at the end of the first knitting operation.

With the present construction, mechanism has been provided which is controlled automatically from the pattern chain after the knitting of a few courses of the welt portion of the fabric to position and tension a welt wire of ordinary description against the fabric, so that during the continued knitting of the welt the fabric will be drawn beneath and beyond the welt hooks entirely under the influence of the regular fabric take-up tension, while the hooks are brought to rest in an intermediate position until they are again advanced to return the initial loops of the welt portion of the fabric to the needles to turn the welt. The mechanism for guiding the welt wire into operative position for each section of the machine comprises two welt wire guideways 430 (see Figs. 3, 4 and 7) which are positioned at opposite ends of the section slightly beyond the end needles and are rigidly secured to the table 124. These guideways which are in the form of hollow grooves open at each end, occupy a horizontal position for the greater portion of their length, being turned sharply upwards at their inner ends adjacent the needles. There is provided in the upturned portion of each guideway 430 a trip lever 432 pivoted at 434 on the guideway and normally positioned with the upper end blocking the guideway. After the machine has been put in operation and during the knitting of the first few courses of the welt, the operator will place a welt wire for each section of the machine in position in the guideways so that it rests upon the upper ends of the trip levers 432 and will attach to each end thereof the usual fabric take-up straps (not shown) secured to the take-up bar 436. Each of the trip levers 432 is provided at its

lower end with a hook 438 which is arranged upon movement of the upper end of the lever from under the welt wire to swing into position to engage with and arrest the further downward movement of the welt wire under the pressure of its take-up straps just out of contact with the fabric. A control rod 440 to which is fastened a spring 442 normally holds each of the levers 432 in the operative position illustrated in Fig. 4. To enable the welt rod to fall down, the upwardly extending end of the guideways 430, each control rod 440 contacts with a lever 444, a rod 446 extending throughout the machine length supporting two of these levers 444 for each section of the machine. There is also rigidly fastened to this rod 446, a downwardly extending lever arm 448 which is adapted for engagement with a bell-crank lever 450 which is pivoted on the regular fabric take-up release mechanism stud 452. As is well known, all Cotton machines are equipped with a fabric take-up release mechanism which functions at each narrowing. This mechanism takes the form of a lever 454 which is actuated by a cam on the main cam shaft 102, and has pivoted to one arm thereof a rack bar 456 which is formed with teeth at its upper end for contacting with a ratchet wheel 458 rigidly fastened to the fabric take-up shaft 436. A spring 460 is provided for holding the lever 456 against an adjustable stop screw 462, which is supported by an extension from the lever 454. During the narrowing or any time that the cam shaft 102 is shifted endwise, the entire assembly described will be lifted by the usual take-up release cam (not shown), so that the teeth of the rack bar 456 engage with the ratchet 458 and so cause the take-up shaft 436 to move in a counter-clockwise direction and thereby relieve the usual take-up action. It is this motion that is taken advantage of in the present instance to move the lever 448 so that the rod 446 will be oscillated in a clockwise direction and so cause the levers 444 to move with their upper ends in a direction toward the right (Fig. 4), in this manner moving the control rods 440 to the right and the levers 432 so that their upper ends will move out of the groove of the welt wire guideway 430 and enable the welt wires supported by these levers to fall down the groove and contact with the hooks 438 which, due to the movement of the levers just described, have been projected into the welt wire grooves, so that the welt wires are momentarily prevented from continuing down the groove. The object of their being held here momentarily is to prevent the sudden application of the take-up. However, as soon as the lever 454 moves off its cam in a direction toward the cam shaft 102, the levers 444 and intervening connections are permitted to move under the influence of the spring 442 to withdraw the end hook 438 from the groove of the welt wire guideway 430, and so permit the welt wires to gently finish their downward movement to a point where the wires contact with the fabric stretched between the needles and the welt hooks. The object of controlling the operation of the welt wires from the ordinary narrowing fabric release mechanism, is to eliminate the necessity of adding control mechanism to the regular control chain, which in commercial machines already controls numbers of devices, so that it is difficult to add more mechanism to it. It is planned in this instance to make a dummy narrowing motion with the narrowing points racked out beyond the needle bed width, which is their customary position during the knitting of the welt and while at

- each subsequent narrowing operation the lever 448 will oscillate the rod 446 and so move the levers 432, such movements will be dummy insofar as the operation of the welt wire is concerned, as narrowing does not take place until after the turning of the welt.
- Assuming that all the mechanisms are in position, as shown in the various figures, with the needles in the raised position prior to yarn sinking, as shown in Fig. 4, the previous stocking cast off the needles and still lying on the table 124 of the machine, the welt rod and fabric wrapped around the take-up roller 437, the take-up roller disconnected from its fabric take-up counter-weight as is usual after casting off a stocking, and the chain racking mechanism having been set with the double set-up chain bump, that is, the chain bump wide enough to act on the end 176 of the lever 170 and the end of the lever 396 (Fig. 12) simultaneously, in position just prior to its operating on these levers, as shown in Fig. 12, the operator manually traverses the ordinary yarn carriers from their normal idle position at the right of the machine to the end of their stroke on the left end of the machine, when the machine is standing still, thereby laying the yarn for the initial course over the noses of the sinkers 322 and 324, and thereafter couples this carrier to its friction drive in the ordinary manner, with the slur cocks standing at the right hand side of the machine. The operator then places his foot on the regular foot pedal 500 (Fig. 12) and presses downward as is customary in racking the chain drum ahead to get the idling chain bump out from under its regular racking pawl following the usual practice at the start of a stocking. By so doing, the double chain bump above referred to, operates to move the lever 170, the height of this bump being sufficient to lift the latch 158 (Fig. 1) off the surface 160 of the lever 156 and place it in position so that as the spring 184 moves the lever 156, its surface 180 contacts with the end of the latch 158, thereby moving the shift roller 142 in line with the shift cams 186. At the same time the double chain bump is moved under the end of the lever 396 (Fig. 12), thereby moving the loose course roller 380 in line with the loose course cam 378, which at this time is in position with relation to its roller as shown in Fig. 60, so that it can be readily shifted as noted. This shift of the loose course roller does not disengage the lever 414 from between the end of the regulating screw 404 and the lever 402 as its end is tightly held, the moving of the roller 380 merely tensioning the spring 420 (Fig. 12). The operator then applies power to the machine, which commences to rotate its main cam shaft 102 and the supplementary or welt cam shaft 132, both rotating in a clockwise direction as shown in Fig. 1. As soon as the shift cam 186 contacts with the roller 142, the cam shaft 132 commences to shift to the right, from the position shown in Fig. 3. The Coulier motion immediately commences to kink the yarn by moving the slur cocks 334 from right to left, thereby camming the jacks 332 and successively moving the jack sinkers 324 toward the needles and against the verge plate 330, the loose course roller 380 (Fig. 60) immediately rising to the high surface of the loose course cam 378, thereby placing the needles in a direction toward the press the required amount necessary to enable the jack sinkers to measure the desired length of yarn for the initial setting-up loose course.
- Upon continued rotation of the machine, the

sinking of the yarn continues while the cam shaft 132 continues to shift to the right from the position shown in Fig. 3, so that the disk 246 moves sideways with relation to the idling roller 244 and places the cam 238 in line with the rollers 236, at the same time shifting the disks 224 of the vertical motion, sideways in relation to their idler rollers, placing the rollers 216 in line and on their operating cams 218, at the same time moving the idling disk 272 for the pendulum horizontal motion link 260 out of contact with the end 268 of the link, thereby permitting the end 268 of the link 260 (Fig. 4) to drop down and engage with the pendulum pin 264, the pin 270 of the link 260 (Fig. 3) thereby being placed in the path of the cam 278, the pin 270, however, not contacting with the cam 278 at this time, as the end 268 of the link 260 rests on the pin 264 (Fig. 4) at this time, the spring 274 so holding the link. The relation of the rollers 216 and 236 and the pin 20 270 to the cams at the starting of the power operation of the machine are as shown in Figs. 14 and 15, the cams rotating in relation to the rollers and pin during the shift of the cam shaft 132, so that the cam shaft is fully shifted before the 25 roller 236 comes to the end of the radial surface of its cam 238 and before the roller 216 reaches the decline of its cam 218, the pin 270 lining up with its cam 278 considerably before it comes to its decline.

Upon continued rotation of the machine and while the jack sinkers are still being cammed in to kink the initial course of yarn, the roller 216 rises on its incline (a) while the roller 236 moves down its decline (a) thereby causing the hooks 35 to move through a path as shown in the dotted lines at the left side of Fig. 16, so that the rollers are simultaneously at their (b) positions, which correspond to the (b) position of the hooks (Fig. 16).

Rotation of the cam shaft continues the jack sinker kinking of the initial course of yarn, the roller 216 riding down its decline to the position marked 16 which corresponds to the position of the hooks shown in solid lines in Fig. 16. At the 45 time that the hooks reach the position marked (c) (Fig. 16), the end plates 284 (Figs. 9 and 10) contact with their surface 318 and later their flat end surfaces against the screws 314 which are, as previously noted, rigidly and adjustably 50 supported in the welt wire guideways (Fig. 4), in this manner centralizing the hooks between the sinkers, as shown in Fig. 57 and as shown in Fig. 47, the pointed ends formed at the bottom of the hooks 283, as shown in Fig. 57, materially assisting in deflecting any sinkers or in a later movement of the hooks, any knockover bits that may be out of line.

The end 302 of the left hand plate 284 which is shaped as shown in Fig. 10, passes between the 60 yarn and the press edge of the machine, that is, the yarn at this time is between the depending end 302 of the left hand plate and the needles, lying about opposite the point 501 of the plates. The plate is cut away at this point so as not to 65 clamp the yarn between the plates and the last needle of the section; the end 302 of the plates is guided to position the hooks to the press edge of the machine by contacting with the beveled upper edge 303 of the press edge 502 (Figs. 10 70 and 16). The roller 236 moves from its (b) position to a position marked 16 on Fig. 14, although it may, with its roller 236, rest on its cam in the 16 position as long as the cam guides the end plates 284 up to a point where they contact with

the edge 303, as it is important that the hooks in the position shown in Fig. 16 rest against the press edge and so be as far removed from the shanks of the needles as is possible, the end plates 5 284 being cut away at 504 (Fig. 10) so that they do not contact with the press edge, in order to ensure that the hooks rest directly against the press edge, as shown in Fig. 16, the jack sinkers in the meantime having continued to kink the yarn 10 for the initial course.

Upon continued rotation of the machine, yarn kinking continues with the roller 216 riding from its 16 to 17 position, the surface of its cam at this point being radial so that the vertical position 15 of the hooks is not changed, whereas the roller 236 in moving from its 16 to 17 position moves the hooks toward the needles, the cheeks thereby straddling their respective needles, as shown in Fig. 17, the slightly inwardly bent tips of the 20 cheeks (Fig. 57) snapping by the needle shanks. At this time the last jack sinker has kinked its yarn, the pin 374 (Fig. 8) having in the meantime contacted with the extension 372, thereby having raised the latch 358 and permitted the 25 jack bar 338 to snap inwardly against the jacks by the action of its spring 356, in this manner rigidly holding the jack sinkers 324 against the verge plate 330. This locking inwardly of the jack sinkers takes place immediately after the last 30 jack sinker is cammed against the verge plate by its jack 332 and slur cock 334.

The purpose of locking in the jack sinkers at this time is to prevent the backing out of the jack sinkers in the subsequent movement of the 35 hooks as they engage with the initial course.

On continued rotation of the machine, the roller 216 rises on its incline (c) (Fig. 15) from its 17 to its 18 position, while the roller 236 rides on the radial portion (c) of its cam and just before reaching its 18 position commences to fall off, as shown in Fig. 14. The relative effect of 40 these movements on the hooks is to raise them into the position shown in Fig. 18, in which position the right hand cheek has moved between the initial course of yarn and the needle shank, as shown in Fig. 48, the jack sinker being shown in solid black lines in Fig. 47, both cheeks having therefore engaged the bar of yarn (a) (Fig. 48) in the throat, the bent-in tips of the cheeks 307 (Figs. 46 and 47) ensuring that the right hand 45 cheek does not pierce or otherwise engage with the b bar of yarn of the initial course (Fig. 48).

The falling away of the roller 236 from its cam, as it goes into its 18 position (Fig. 14), serves to 50 remove the cam from roller contact as the hooks 283 position the initial course of yarn in their throats, this falling away not taking place, however, until the cheeks 307 have with certainty 55 passed upwardly in relation to the initial course of yarn high enough to ensure that the inwardly bent tips (Fig. 57) will not catch on the yarn and so that this inwardly bent point of the cheeks is firmly positioned to the back of the needles as the cheeks pass the yarn on their upward movement, so that when the hooks are in their Fig. 18 60 position, the springs 230 (Fig. 4) tension the hanger so that the hooks tension the initial course of yarn between the jack sinkers and the hooks, holding the kinks of yarn taut for the 65 next operation.

As the machine continues to rotate, the needles 70 commence their downward motion. At the same time the in and out position of the needles is affected by the loose course roller 380 falling down its incline 408 (Fig. 60). It is understood 75

that the lever 414 (Fig. 12), as soon as the loose course roller reaches the high portion of its cam 378, moves out from between the regulator screw 404 and the lever 402 (Fig. 60), so that the regulator motion does not interfere with the movement of the needles away from the press at this time due to the space provided between the regulator screw 404 and the lever 402 by the moving away of the lever 414. As the needles move downward and away, as shown in Fig. 19, 10 the roller 216 moves downward slightly, the hooks continuing to tension the kinked yarn of the initial course, while the dividing sinkers 234 (Fig. 19) move toward the needles; the cam 238 (shown in Fig. 14) being cut away so as not to 15 interfere with the tensioning of the initial course, the roller 236 does not contact with the cam at this time. The initial course of yarn at this time (Fig. 19) therefore is positioned as shown in Fig. 49, the dividing sinkers 322 as shown in 20 this figure, not having contacted with the initial course of yarn.

During the movement of the cams from the 19 to the 20 position (Figs. 14, 15) no effect is produced on the hooks, which continue to hold 25 the setting-up course taut, the needles continue to move downwardly, the loose course roller 380 rides on its high surface (Fig. 60), the regular needle in and out roller of a regular Cotton type machine having at about this time just come in 30 contact with its cams, ready to take over the work of moving the needles in and out in the normal manner, the dividers 322 as shown in Fig. 20, having contacted with the initial course of yarn and positioned it as shown in Fig. 50, the lower 35 tip end of the beards of the needles being at the same time well above the initial course of yarn, as shown.

As the cams move from their 20 to their 21 position, no change takes place in the position of 40 the hooks as the cams 218 and 238 are radial at this point, the initial course of yarn continuing to be held taut at the same time, the needles continuing downward and moving toward the hooks as in their normal course of operation, the position of the cheeks 307 being such that the tip of the beards of alternate needles b not affected by the initial course of yarn, as shown in Figs. 50 and 21, can move between the cheeks 307 of the hook members, the tip of their beards being well 45 above the initial course of yarn, but below the upper inwardly bent-in tips of the cheek members, in order that there will be no interference or entanglement of the beards with the cheek members. The intermediate needles between the 50 alternate needles b (Fig. 50) due to the movement of the needles toward the hooks and the press edge of the machine, contact the initial course of yarn with their shanks and are so prevented from moving inwardly in line with the alternate needles b, as shown in Figs. 51 and 21, in this manner insuring that the initial course of yarn is laid tightly against their shanks below the tip of their beards, so that upon movement of the needles 55 downwardly into their Fig. 22 position, the initial course of yarn will be positioned inside the beards of every other needle that contacted with the yarn, as shown in Fig. 22, while the beards of the alternate needles b, as shown in Fig. 51, move 60 downwardly between the cheeks of the hook members clear of the loops held on the hooks. With a loose course of the proper length, the alternate needles b will be well clear of the hooks. However, if the yarn sinking mechanism should be set 65 to produce a relatively short course upon the 70

- set-up, thus forcing the needles between the cheeks 307, the needle beards will be closed or pressed by engagement with the shanks of the hooks to prevent them from taking yarn. The 5 rollers 216 and 236 (Figs. 14 and 15) in the movement from 21 to 22 are riding on the radial surface of their cam, and so do not affect the position of the hook members which still hold the initial course of yarn taut.
- 10 It is to be remembered that as soon as the loose course roller 380 moves off its surface 408 (Fig. 60), it tries to move out of line with the loose course cam 378, but is prevented from fully doing so due to the lever 414 (Fig. 12) being unable to pass freely between the regulator screw 404 and the lever 402, but will do so as soon as the regulator roller 398 moves to the low part of its cam (Fig. 60).
- 15 The needles then continue moving downward, 20 the catch bar 376 (Fig. 1) having in the meantime, as in the normal course of operation, engaged with the divider and jack sinker butts as usual and commenced withdrawing the sinkers, thereby taking out the disalignment existing between the needles and forming the initial course of yarn about as shown in Fig. 52. The tips of the 25 beards at this time are well below the yarn level so that even though the beards of the needles in line with the hook members contact the yarn, 30 as shown in Fig. 52, they do so without in any way affecting the formation of the set-up.
- It is during the movement of the cams 219 and 239 (Figs. 14 and 15) from their 22 to 23 position that the pin 270 of the link 260 which has until 35 now been regulating the horizontal position of the hook members, contacts with incline *d* of cam 278 (Fig. 14) and lifts the end 262 of the link 260 out of contact with the hanger pin 264 (Fig. 4), thereby disconnecting the pendulum from the 40 cam operating means, in this manner permitting the counterweight 204 (Fig. 4) to try to move the hanger and the hooks in a direction toward the needles, but as the needles are still in too high a position, as shown in Fig. 23, to permit 45 the hooks 283 to pass to the back side of the needles, the only effect this counterweight has is to lay the hooks 283 against the needles, which continue to move downwardly, as shown in Fig. 24, the hooks 283, due to the counterweight movement 50 of the pendulum and hooks in a direction toward the back of the needles, rest against the surface 308 (Fig. 59).
- In this movement of the cams from positions 55 23 to 24, the hooks have been slightly raised in order not to contact with the surface 503 of the press edge, as is clearly shown by the slight rise on the cam 218 (Fig. 15), while the cam 238 of the horizontal motion, as shown in Fig. 14, is merely cut away and has no further effect on 60 horizontally positioning the hooks, as the link 260 remains disconnected from the hanger pin 264, due to the pin 270 continuing to ride up the incline *d*, of its cam 278.
- 65 The normal beard pressing having taken place while the needles are in the position shown in Fig. 24, without however producing any useful effect, but not in any way disturbing the initial course, the needles move downwardly and away from the press, as shown in Fig. 25, the hooks 283 remain at about the same vertical position as shown in Fig. 24, due to their cam 218 (Fig. 15) being radial between the points marked 24 and 25, and as the link 260 remains disconnected from 70 the hanger, the hooks 283 rest against the hooks

of the needles, as shown, due to the action of the take-up weight 204.

Continued rotation of the machine moves the needles into the position shown in Fig. 26, the hooks 283 moving in a horizontal and downward direction with them as the initial course is connected to them and the alternate needles, as shown in Fig. 55. The hooks move downwardly as shown by the decline of their cam 218 (Fig. 15) between the points 25 and 26, being by preference so adjusted as to hold the initial course taut, the springs 296 (Figs. 9 and 10) breaking the connection if necessary between the stop pin 295 and the bell-crank 281, and so permitting the hooks to follow the needles vertically in case the setting-up course has been shortened for any reason or due to the hooks standing slightly too high. It is this tautness of the setting-up course that prevents the take-up action of the pendulum from bringing the hooks 283 to the back of the needles.

The needles and sinkers then continue their movement into the position shown in Fig. 27, the hooks continuing to follow the needles. The cam 218 (Fig. 15) between the points 26 and 25 27 is so shaped as to not over-tension the initial course, although as stated before the springs 296 (Figs. 9, 10) will compensate for any reasonable out of adjustment.

The needles and sinkers then move into the 30 position shown in Fig. 28, while the hooks continue to keep the initial course relatively taut, being lowered to compensate for the lowering of the needles as shown by the cam contour 218 (Fig. 15) between the points 27 and 28, and it will be 35 observed that the hooks remain well above the knockover bits, as it has not been found desirable to move the hooks between the knockover bits at a point so far removed from their supported ends (Fig. 28) as they are so thin that they are 40 readily disaligned.

The needles and sinkers then move into a position shown in Fig. 29, the hooks following them. The hooks are beginning to move toward the back of the needles, but still do not enter between the 45 knockover bits. The slight movement toward the backs of the needles (Fig. 29) is a result of the slight decline between the points 28 and 29 of the cam 218 (Fig. 15).

The needles and sinkers then move to the position shown in Fig. 30, the hooks moving downward and so registering between the knockover bits, being assisted in so doing by their bottom extremities and the fact that the end plates 310 have kept the bar 282 and the hooks relatively 55 centered between the knockover bits by being in contact with the adjusting screws 314 (Fig. 3).

The needles then move to the position shown in Fig. 31, the hooks due to the action of the hanger take-up counterweight 204 (Fig. 4) holding the 60 hooks to the back of the needles and the initial course of yarn taut, as shown in Fig. 54, the sinkers as the needles rise holding the yarn down so that it cannot rise with the needles, the vertical elevation of the hooks remaining as in Fig. 30, as indicated by the relatively radial shape given the cam 218 (Fig. 15) between the points 30 and 31.

The needles thereafter continue their upward 70 motion, as shown in Fig. 32, with the hooks maintaining the now fixed hook elevation due to the cam 218 (Fig. 15) being relatively radial. This finishes one cycle of movements of the knitting instrumentalities which will be followed by the 75

regular second course of yarn sinking and needle movements.

During these movements of the needles to the 33 position, the loose course roller 380 has disaligned itself from its loose course cam 378, the chain bumps have been racked out from under the levers 396 and 170, the lever 414 has entered between the regulator screw 404 and lever 402, the cam 150 (Figs. 1 and 3) has acted upon the 10 roller 146, thereby moving the cam shaft shift lever 138 back to the position shown in Fig. 1, where it is again in line with the cams 152 and 154 and the latch 158 (Fig. 1) can again move downward into engagement with the surface 160 of the 15 shift lever 156, so that upon continued rotation of the cam shaft the cam 154 can contact with the roller 142 and shift the cam shaft 132 back to its neutral or idle position, as shown in Fig. 3, thereby having again positioned the idling rollers 244 20 and 222 on their respective disks 246 and 224 (Fig. 8) and so taken the rollers 236 and 216 out of engagement with their cams. This is possible because the rollers are, at the time of the shift, on the circumferential portion of their cams some- 25 where between the lines 32 and 35 (Figs. 14 and 15), and the radius of the cams is such as to permit the shifting of the active rollers from their cams to the inactive rollers and their disks to take place. The pin 270 of the link 260 is at the 30 shift held on the outer periphery of its cam 218 (Fig. 14) so that its surface 268 (Fig. 3) can be positioned on its idling disk 272, in this manner of holding the hooked end 262 of the link 260 out of engagement with the pin 264 of the hanger, as 35 shown in Fig. 4, and permitting the counter-weight 204 to tension the hanger away from the needles during subsequent knitting, without interference or the addition of mechanism weight to the necessarily delicate fabric take-up re- 40 quired.

The catch bar 376 has at the proper time during the cycle moved the sinkers away from the needles, and in the normal manner retracted them to the position shown in Fig. 4, thereby having positioned the jacks 332, as shown, and as the jacks contact with the bar 338, brought the same out into a position where it can again be locked with the latch 358, as it is not intended to use this jack bar during normal knitting, although 50 it might well be locked and unlocked at each cycle to hold the sinkers against the verge plate or operate in any well known manner from cams so that every jack sinker kinked across can be held from being displaced prior to the incoming of the 55 catch-bar-driven divider sinkers.

After starting the cycle of operations just explained, immediately after the hooks are in a position shown in Fig. 32, the operator can remove the last knitted set of legs which were cast off 60 prior to the set-up and left lying on the bed of the machine wrapped around the regular take-up rollers. While removing the legs from the take-up rollers 431 around which they have been wound, along with the welt wire, it is intended 65 that the operator shall take each welt wire and lay it into the open end of the groove of the welt wire support 430, against the top end of the levers 432, attaching thereto the two regular fabric take-up straps which as is well known in cotton 70 machines are a form of elastic strap having hooks at their free end, their other end being permanently attached to the respective take-up rollers 437, and thereafter, after so doing at all sections, winding up the regular take-up counterweight. 75 Regular knitting then continues with the

cam shaft 132 in the position shown in Fig. 3, the lever 414 (Fig. 12) having fallen into the position between the regulator screw 404 and the regulator lever 402, as shown in Figs. 12 and 60, so that the needles will be positioned by the regulator cam 400 for correct loop length in the normal manner, the hooks 283 vibrating back and forth as the needles move to and from the press in their normal process of knitting, these hooks 283 taking up the fabric and holding it with the required degree of tautness and yet in a delicate manner, as shown in Fig. 33, until just prior to the time the hanger pin 212 (Figs. 1 and 3) contacts with the pendulum stop hook 210 (Fig. 1) at which time a length of fabric somewhat like that shown in Fig. 33 has been produced. At about this time the chain control mechanism which has been racked a tooth for each rotation of the machine, as is customary in Cotton machines, causes the narrowing machine to go into 20 a dummy motion, that is, a regular narrowing motion except that the narrowing point units used for narrowing the leg are racked outward beyond their respective needle sections, which causes the lever 50 (Fig. 4) to be acted upon by 25 the regular take-up slack-back mechanism assembly of parts including lever 454 and rack 456, thereby oscillating the rod 446 and through the levers 444 pulling the control slides 440 so that the welt rod levers 432 are moved permitting 30 the welt wires that were resting on the top of these levers 432, to fall down the inclined portion of the guideway 430, the rods catching against the hooks 438 of their respective levers 432. This arresting of the downward motion of 35 the welt wires occurs just prior to their contacting with the fabric stretched, as shown, between the hooks and the needles in Fig. 33, so that the wires do not come in contact with the fabric to suddenly exert an overtensioning effect on the 40 fabric. As soon as the fabric slack-back mechanism falls off its cam, the lever 448 rocks the rod 446 in counterclockwise direction, therefore 45 causing a withdrawal of the end hooks 438 of the levers 432 out of the path of the welt rod guideway 430, and permitting each welt wire to fall the remaining short distance so that it can contact with and tension the fabric under the pressure of the take-up straps and take-up 50 rollers 437. The grooves in the flat portions of 55 the guideways 430 are made large enough to permit an unrestricted vibration of the welt rod, attached with its bands to the take-up rollers 437, so that the welt wires are rendered operative to take over the work of tensioning the 60 fabric as the hanger pins 212 contact with their respective stop hooks 210 to arrest the further outward movement of the several hangers and the welt hooks mounted thereon. When the dummy narrowing motion is finished, knitting 65 continues automatically as in the normal operation of Cotton type machines.

When the required amount of fabric has been knitted to form the welt, the control chain racking mechanism having in the meantime continued to rack the control chain, a bump somewhat similar to the chain bump 178 (Fig. 12) only higher is brought under the surface 176 of the lever 170. As this bump is higher than the one used in the set-up, it raises the latch 158 70 into a position high enough to contact with the surface 182 of the lever 156 (Fig. 1), the lever 156 moving toward the latch 158 due to the action of its spring 164, thereby moving its roller 142 into a position to align this roller with the 75

cam 188 (Figs. 1 and 3). The roller 142 moves into this position where the various shift cams on the disks 134 and 136 are cut away or when about reaching the position as shown in Fig. 1.

- 5 Upon continued rotation of the machine, the normal process of knitting continues, the needles having yarn kinked around them as in regular knitting, the roller 142 contacting with the shift cam 188 and shifting the cam shaft 132 to the 10 left from the position in which it is shown in Fig. 3, thereby moving the rollers 244 off their disk 246 and the rollers 222 off their disks 224 and placing the rollers 217 and 237 in line with and on their respective cams 219 and 239, at the same time permitting the surface 268 of the link 266 to move off its disk 272 and cause the end 262 of the link 266 (Fig. 4) to move downward and into engagement with the hanger pin 264, in this manner placing the welt transfer cams under 20 their respective rollers and coupling the hangers to the operating mechanism. The rollers 237 and 217 are at the time of the shift about in the position shown in Figs. 14 and 15, that is, the roller 237 on the large radial periphery of its cam 239 (Fig. 14) so that it can be shifted and the roller 217 on the small radial periphery of its cam 219 (Fig. 15) so that it can be shifted.

Upon continued rotation of the machine, the pin 237 moves down the cam decline *e* of the cam 239, thereby moving the hooks 283 in a direction toward the needles from their intermediate position in which they have been standing during the knitting of the welt fabric. The action 30 takes place while the kinking of the next course 35 is taking place, as shown in Fig. 35, while at the same time the roller 217 maintains the elevation of the hooks about as shown in Fig. 35 until the roller 217 (Fig. 15) contacts with the slight incline *d* of its cam 219, thereby lifting the hooks 40 as shown in Fig. 36, in order that the hooks will with certainty be lifted clear of the under part of the welt fabric and so that the edge hooks of the section will with certainty clear the selavage edges of the fabric which are usually rolled to a greater or lesser extent and therefore require a hook lift to ensure that the end of the hooks and the fabric do not contact.

Continued rotation of the cam shaft and continued action of the regular knitting elements to 50 the position marked 36 on the cam drawing (Fig. 14) continues moving the hooks in a horizontal direction toward the needles to the position shown in Fig. 36, while the hooks remain in about the same elevation previously noted, if anything 55 rising slightly before the roller 217 comes into its 36 position, as shown in Fig. 15, in order to lift the hooks still higher to ensure that they do not engage with the under part of the welt fabric. The newly kinked yarn for the next course is at 60 the same time almost in position to fall off the nose of the sinkers, as shown in Fig. 36, the knockover bits rising at just about the same time, as is common in modern Cotton machines, without however having any effect on the welt apparatus.

As the machine continues to rotate, the needles draw the newly kinked yarn off the nose of the sinkers, as shown in Fig. 37; the hooks remain at about the same elevation and move 70 nearer to the needles due to the slight decline of the surface of the cam 239 between 36 and 37, as shown in Fig. 14, the elevation of the hooks remaining the same due to the surface of the cam 219 between the points 36 and 37 being relatively radial.

Upon continued rotation of the machine, the needles move downwardly enough to at least partially draw the previously kinked yarn through the old loops in the regular manner, as shown in Fig. 38; the roller 239 continues to move down its decline to its 38 position, as shown in Fig. 14, thereby positioning the hooks somewhat to the beard side of the needles as shown in Fig. 38, while at the same time the elevation of the hooks remains the same, as it is desirable that the hooks do not 10 enter between the knockover bits until somewhat later or until the hooks have more nearly approached the supported end of the knockover bits so that should some of the knockover bits be disaligned, the hooks will be able to center the knockover bits and be guided by them as the tapered bottom extremities of the hooks engage and center themselves accurately and certainly between the knockover bits, regardless of whether the bits are straight or bent. The hooks therefore are moved as far as possible toward the supported end of the knockover bits before they attempt to enter and move between them, care being exercised at this point to see that the hooks are low enough to ensure the top fabric of the welt moving freely under the nose of the sinkers and yet not have the hooks contact with the knockover bits, as shown in Fig. 38.

As the machine continues to rotate, the needles move toward the press edge of the machine, as shown in Fig. 39, following a decline on the cam 239 (Fig. 14) between 38 and 39, the roller 217 moves down a decline between 38 and 39 of its cam 219, so that the pointed bottom extremities of the hooks 283 enter between the knockover bits.

Upon continued rotation of the machine, the needles continue to move toward the press, sliding their loops on the inner curve of the knockover bits, as shown in Fig. 40, thereby finishing 40 the previously knitted course as is common in machinery of this type, while the roller 237 continues to move down the decline of its cam 239 between the points 39 and 40 (Fig. 14), thereby 45 positioning the hooks against the press edge, as shown in Fig. 40; the cam decline continues beyond this point in order that the roller 237 may leave the contact of its cam 239 to ensure that the hooks 283 will with certainty be positioned and rest against the press edge, the spring 230 50 (Fig. 4) of the horizontal operating mechanism for the pendulum ensuring that the hooks are rigidly held against the press edge as shown. At the same time, the roller 217 (Fig. 15) moves down the sharp decline of its cam 219 between 55 the points 39 and 40, thereby projecting the hooks 283 downwardly between the knockover bits to the position shown in Fig. 40, so that the hooked ends of the needles can by moving toward the hooks and upwardly enter between the 60 cheeks 307 of the hooks 283, the position of the hooks being such as to ensure that when the needle hooks contact with the surface 308 of the hooks 283 (Fig. 60), they will flex the needles to ensure that all the hooks will be tightly held 65 against the surface 308.

As the machine now continues to rotate, the hooked ends of the needles move into position between the cheeks of the hooks 283. It is understood that the hook members are positively centered between the sinkers and the knockover bits, more particularly as there is enough clearance 70 between the end plates 284 (Figs. 9 and 10) and the positioning screws 314 (Fig. 7) to enable the sinkers and knockover bits to complete the posi- 75

tioning of the welt bar 282, and as the hook members 283 fill or nearly fill the space between the knockover bits and the sinkers, it follows that when the needle hooks are moving from the 5 position shown in Fig. 40 to the position shown in Fig. 41, they will with certainty enter between the cheeks 307 of the hook members 283 (Fig. 60), the cam 239 being out of contact with the roller 237 ensures that the hooks will remain in 10 a fixed and known position against the press edge of the machine, while the vertical position of the hooks remains the same, as shown in Fig. 40, due to the cam 219 being radial between the points 40 and 41 as shown in Fig. 15.

15 As the machine continues to rotate, the needles as in normal knitting move upwardly to the position shown in Fig. 42, having thereby entered the loops of the top fabric of the welt which have been held open by the cheeks 307 20 of the hook members 283, the hooks remaining in contact with the press edge of the machine as the cam 239 still fails to contact with its roller 237 during the movement between the 41 and 42 positions (Fig. 14). During this time, the 25 hooks commence their downward motion due to the decline of the cam 219, as shown in Fig. 15, the downward movement of the hooks not taking place, however, to any appreciable extent until the top of the hooks of the needles are 30 above the bottom line of the sinkers, in order that the loops that are being transferred to the needles may with certainty be positioned on the needles before the cheeks 307 of the hooks 283 move downward, out of these loops.

35 Further rotation of the machine causes the needles to move into the position shown in Fig. 43 while the hooks are still held against the press edge of the machine, due to the cam 239 between the points 42 and 43 not having contacted the roller 237. At the same time the roller 219 continues to move down the decline of its cam 217 between the points 42 and 43 (Fig. 15) and so causes the cheeks of the hook members to move out of the loops of the upper portion of the welt fabric, as shown in Fig. 43, thereby having fully deposited the initial course of loops on the needles, which then continue to rise into the position shown in Fig. 44 while the hooks during this movement also commence their upward motion, following the cam incline between 43 and 44 (Fig. 15). The hooks still rest against the press edge of the machine as the cam 239 still does not contact with the roller 237 (Fig. 14).

Continued rotation of the machine causes the 55 needles to continue their upward movement into their 45 position, the hooks are lifted as the roller 217 rises on the incline of its cam 219, and at about this time the roller 237 commences to contact the decline of its cam 239 again so that 60 as the hooks are lifted above the press edge of the machine, as shown in Fig. 45, the spring 230 (Fig. 4) is permitted to move the hooks away from the needles, only enough to cause a safe clearance between the cheeks of the hooks and the beards of the needles, so that no entanglement 65 or interference can take place. Thereafter the needles become positioned as shown in Fig. 46, while the hooks are lifted over and to the back of the needles, as shown in dotted lines in Fig. 70 46. The needles are then in position to have the sinkers kink the next course of yarn and then to knit in the normal manner.

Continued rotation of the machine causes the 75 cams 219 and 239 to give the hooks the motion shown in dotted lines in Fig. 46. By having the

roller 217 ride up the incline and down the decline of its cam 219 (Fig. 15), the roller 217 reaches the position on the small radius of its cam, as shown in Fig. 15, while the roller 237 rides up the incline of its cam 239 to the large 5 radial surface, as shown in Fig. 14, thereby placing the rollers again in about the position as shown in dotted lines in this figure. As these rollers are brought to the positions just noted, the cam 150 (Fig. 1) has contacted with the 10 roller 146 (Fig. 3) and moved the lever 138 with its roller 142 outwardly so that the surface 160 of the lever 156 can be acted upon by the latch 158 (Fig. 1), as the latch spring 164 acts 15 to draw the latch downwardly, the chain bump under the surface 176 of the lever 170 (Fig. 12) having in the meantime been racked during the just described cycle of knitting. The roller 142 is thus locked into the position shown in Fig. 1, so that upon continued rotation of the cam 20 shaft 132, the cam surface 152 of the shift cam 134 (Fig. 3) can contact with the roller 142 to shift the cam shaft 132 to neutral position. The cams 219 and 239 are moved out from under 25 their rollers 217 and 237 respectively while at the same time the idler disks 224 and 246 pass under the idler rollers 222 and 242 (Fig. 3) to leave the welt hook actuating mechanism in its neutral inoperative position illustrated in Fig. 1. 30

It is understood that prior to the shifting of the cam shaft, the end 68 of the link 260 (Figs. 1 and 3) has contacted with a cam 510 formed on the side of the disk 272 and lifted the link 260 (Figs. 4 and 14) so that its end 262 is lifted 35 out of contact with the hanger pin 264, the pendulum therefore resting with its stop pin 212 against the pendulum stop hook 210, its counterweight 204 effectively holding it in this position as shown in Fig. 4. The fact that the link 260 is disconnected from the hanger, enables the operator during the subsequent knitting of the leg and the remainder of the stocking to at any time lift the stop link 210 of any section and so enable the hanger to be swung into the dot and dash position shown in Fig. 4 for inspection, for reasons of maintenance or for any other purpose. The operator must, of course again manually lock the pendulum into the position shown in 40 solid lines in Fig. 4 prior to the commencement of the next stocking. It is understood that normally the pendulums would rest during the knitting of the balance of the stocking in the position shown in solid lines in Fig. 4, as it is from this position that they can be moved through 45 their motions at the next setting-up operation. 50

The machine herein disclosed having the construction and mode of operation above set forth for producing automatically a turn welt fabric, is particularly well adapted for use with multiple section flat full-fashioned machines to improve the operation and efficiency of these machines, so that they can be operated substantially continuously and with very little attention from the operator. The construction illustrated permits the operation on a new set of stocking 60 blanks to be begun with the previously knitted legs still wound on the take-up rollers, and permits the operator to remove the previously knitted legs, to position the welt wires in the machine, and to attach the welt take-up straps thereto 65 at any time during the knitting of a considerable portion of a new welt without interrupting the operation of the machine.

A noteworthy feature of the present invention 70 consists in the provision of substantially inde- 75

pendent welt turning units for each section of the machine which are capable of simultaneous control to perform their required functions and are at the same time capable of independent operation to permit the welt turning devices for each section to accommodate themselves to variations in adjustment or operating characteristics of the several sections. A simple and accurate mechanism is provided for imparting simultaneous vertical and lateral positioning movements to the welt hooks in timed relation to the operation of the machine. Each section, however, is capable of automatic self-adjustment to secure an accurate and efficient operating relationship to the needles and cooperating elements. Each welt bar is separately located lengthwise of the needle series, and is separately tensioned during the knitting of the welt fabric, so that any variations in take-up action due, for instance to differences in length of the fabric knitted on individual sections, cannot have the effect of varying the operating conditions along the whole length of the machine.

The automatic laying-in of the welt wires simultaneously on all the sections of the machine similarly permits the shift to the regular fabric take-up during continued operation of the machine without causing the inequalities in take-up tension from section to section which must inevitably result if the operator were to lay these wires in by hand.

The novel welt hook herein disclosed is desirable from the standpoint of the cost of production, the certainty with which it operates and its adaptability for use in the finest gauges. Attention is called particularly to the pointed shape of its sinker and web holder engaging surface on the back side of the shank (Fig. 59), to the tapered surfaces of the bottom extremity of the hook, and also to the cam surface 308 which enables the hook of the needles to be positioned in a flexed condition and so ensure that the hooks of the needles will with certainty be engaged with the hooks enough and yet not contact with the bar of yarn of the initial course of loops held in the hook throats as the needles rise. Another feature of the hooks is the slightly inwardly upper tips of the cheeks 307 ensuring that the upper pointed ends of the cheeks will with certainty move into the setting-up course without piercing or otherwise mutilating the yarn.

The fact that the hooks 283 are at all times positioned between either the knockover bits or sinkers or both of them, at such times as they must be in line with the needles is a very desirable feature, as it ensures, due to a complete or very nearly complete filling of the space between these elements, that the needle hooks or the needle shanks will with certainty be properly engaged without danger of failure to register at the set-up or transfer.

The fact that the hooks engage with only initial course at every other needle is a very important feature, as it greatly simplifies and cheapens the machine structure and coarsens the gauge of the welt bar, at the same time forming a welt fabric which at its juncture with the body fabric produces a course of loops having anti-run characteristics, that is, holes produced in either the inner or outer portion of the welt cannot run past the welt juncture line, at the same time producing a welt juncture of greater flexibility and expansion than is possible with an every needle welt juncture. It will be under-

stood, however, that certain features of applicant's invention are not limited to an alternate needle set-up, but are of broader application, and that the application is not to be so limited except as specified in the appended claims.

It will be understood that while the several features of the present invention are particularly well adapted for use in a flat full-fashioned machine of the so-called Cotton type for the production of turn welt fabric, certain features are of broader scope and may be applied equally well to other types of machines and for the performance of other operations than that of turning welts on these machines.

Certain features of the invention relating specifically to the construction and arrangement of the welt hook per se, have been made the subject-matter of a separate application which is a continuation in part of this application, Serial No. 133,025, filed March 25, 1937, which has issued to Patent No. 2,134,727, dated November 1, 1938.

The invention having been described, what is claimed is:

1. In a flat full-fashioned knitting machine, the combination with a series of spring bearded needles and yarn sinking devices for measuring kinks of yarn against the needle shanks, of a series of instrumentalities spaced one to cooperate with each alternate needle, arranged for movement relatively to the needles to engage upon said instrumentalities and to lift the initial needle wale kinks from below and over the beards of said alternate needles to form a setting-up course of needle wale loops between said instrumentalities and the intermediate needles.

2. In a flat full-fashioned knitting machine, the combination with a series of spring-bearded needles and yarn sinking devices for measuring kinks of yarn against the needle shanks, of a series of instrumentalities spaced one to cooperate with each alternate needle, arranged for movement relatively to the needles to engage upon said instrumentalities and to lift the initial needle wale kinks from below and over the beards and to the rear of said alternate needles to form a setting-up course of needle wale loops between said instrumentalities and the intermediate needles, and means acting on said instrumentalities for tensioning said loops to the backs of the needles.

3. In a flat full-fashioned knitting machine, the combination with a series of spring-bearded needles and yarn sinking devices for measuring kinks of yarn against the needle shanks, of a series of instrumentalities spaced one to cooperate with each alternate needle, arranged for movement relatively to the needles to engage upon said instrumentalities and to lift the initial needle wale kinks from below and over the beards and to the rear of said alternate needles to form a setting-up course of needle wale loops between said instrumentalities and the intermediate needles, and means for moving said instrumentalities relatively to the needles to take a setting-up course of needle wale loops from the needles.

4. In a flat full-fashioned knitting machine, the combination with a series of needles, and means for sinking yarn about the needle shanks, of a welt turning mechanism comprising a series of loop transfer elements adapted to receive and to return the initial loops of the welt portion of the fabric to the needles, a hanging frame on which said elements are supported to move

freely toward and away from the needles, and a vertically movable pivotal support for said frame.

5. In a flat full-fashioned knitting machine, the combination with a series of needles movable as a unit, and means for sinking yarn about the needle shanks, of a welt turning mechanism comprising a series of loop transfer elements adapted to receive and return the initial loops 10 of the welt portion of the fabric to the needles, a hanging frame on which said elements are supported to move freely toward and away from the needles, a vertically movable pivotal support for said frame, connections including a cam shaft 15 located adjacent said pivotal support on the machine to control said lateral and vertical movements of the hook elements with relation to the needles, and pattern mechanism for controlling the operation of said connections.

20 6. In a flat full-fashioned knitting machine, the combination with a series of needles movable as a unit, and means for sinking yarn about the needle shanks, of a series of loops transfer elements, a hanging frame on which said elements are mounted, a vertically movable pivotal support for said frame, and means for imparting lateral and vertical movements to said frame and elements supported thereon to engage an initial course of loops of the welt portion of the 25 fabric with said loop transfer elements, and thereafter to return said loops to the needles to complete the turning of the welt.

7. In a flat full-fashioned knitting machine, the combination with a series of needles movable as a unit, and means for sinking yarn about the needle shanks, of a series of loop transfer elements, a hanging frame on which said elements are mounted to move freely toward and from the needles, a vertically movable pivotal support for said frame, and means for imparting lateral and vertical movements to said frame and hooks supported thereon to engage and lift from the needles initial needle wale loops, to carry said loops to the backs of the needles during 30 subsequent knitting, and thereafter to return said loops to the needles to complete the turning of the welt.

8. In a flat full-fashioned knitting machine, the combination with a series of needles movable as a unit, yarn sinking devices for measuring yarn about the needle shanks, and a press surface for closing the needle beards, of a series of bifurcated welt hooks having shank portions supported to extend substantially parallel to the 35 needle shanks and shaped to permit the movement of said hooks between the sinkers and between the needles and press edge to engage the needle shanks, a hanging frame on which said elements are supported to move freely toward and away from the needles, a vertically moveable pivotal support for said frame, means for moving said frame and hooks supported thereon to engage said hooks with a course of yarn kinked on the needle shanks, and means for moving the 40 needles forwardly away from the press to disengage said hooks and loops held thereon from the needle shanks.

9. In a flat full-fashioned knitting machine, the combination with a series of needles and their 45 cooperating knitting elements, of a welt turning mechanism including a series of loop taking elements arranged to receive an initial course of loops of the welt portion of the fabric, means for moving said elements to carry the previously 50 formed loops to the backs of the needles, a welt

wire, means for tensioning said welt wire to tension the folded welt portion of the fabric, means for supporting said welt wire on the machine in inoperative position, and means acting when rendered operative to cause said welt wire to engage with and tension the welt portion of the 5 fabric.

10. In a flat full-fashioned knitting machine, the combination with a series of needles and their cooperating knitting elements, of a welt 10 turning mechanism comprising a series of loop taking elements arranged to receive an initial course of loops of the welt portion of the fabric, means for moving said elements to carry the previously 15 formed loops to the backs of the needles, a welt wire, a guideway on which the welt wire can move freely into engagement with the fabric and beyond said elements, means for tensioning said welt wire to tension the welt portion of the fabric engaged thereby, means for supporting said welt wire in the guideway in 20 inoperative position, and means acting when rendered operative to cause said welt wire to engage with and tension the welt portion of the fabric.

25 11. In a flat full-fashioned knitting machine, the combination with a series of needles and their cooperating knitting elements, of a welt turning mechanism comprising a series of loop taking elements arranged to take an initial course 30 of loops of the welt portion of the fabric, means for moving said elements to carry the previously formed loops to the backs of the needles, a welt wire, a guideway on which the welt wire can move freely into engagement with the fabric and beyond said elements, means for tensioning said 35 welt wire to tension the welt portion of the fabric engaged thereby, a latch for supporting said welt wire in the guideway in inoperative position, means for checking the movement of the welt wire into engagement with the fabric, and means 40 acting when rendered operative to operate said latch to release the welt wire for tensioning engagement with the fabric and to check the momentum thereof prior to engagement with the 45 fabric.

12. In a flat knitting machine, the combination of a series of needles, a series of yarn measuring sinkers for forming kinks of yarn successively around each pair of needles, instrumentalities co-operating with the needles to engage with and 50 support fabric loops thereon out of contact with the needles, a bar acting when rendered operative to engage with and hold said yarn measuring sinkers in their fully advanced yarn kinking position, means acting immediately after the completion of said yarn kinking movement of the sinkers to advance said bar into operative position and means for actuating said instrumentalities to engage with the floats of yarn extending 55 across each pair of needles.

60 13. In a flat knitting machine, the combination of a series of needles, a series of jack sinkers, a slur cock for successively advancing said sinkers to kink yarn around the needles, a series of dividing sinkers, a catch bar for advancing said dividing sinkers, a jack sinker bar, and means for advancing said jack sinker bar yieldingly at the completion of the slur cock movement to maintain said jack sinkers in their fully advanced 65 yarn kinking position.

70 14. In a flat knitting machine, the combination of a series of needles, a series of yarn measuring sinkers for forming kinks of yarn successively around the needles, a series of sinker jacks, a slur cock for successively actuating the jacks to 75

- advance the sinkers, a bar arranged to engage said jacks to align the sinkers in their advanced position, and means rendered operative upon completion of the slur cock movement to yieldingly advance said bar to tension the loops against the needle shanks.
15. In a flat knitting machine, the combination with a series of spring beard needles, means for sinking yarn about the needles, and a pressing surface for closing the needle hooks, of means for imparting movements to the sinkers and cooperating movements to the needles to knit fabric courses, a fabric set-up bar comprising set-up elements spaced to cooperate with alternate needles, means for engaging said elements with yarn of a setting-up course to the hook side of the needles, means for moving the needles to an abnormal position forwardly to permit the lifting of said elements and yarn engaged therewith free of the needle hooks, and thereafter for returning the needles rearwardly to their normal operating position.
16. In a flat full-fashioned knitting machine, the combination with a series of needles, means for sinking yarn around the needles and a press surface for closing the needle beards, of means for imparting vertical movements to the needles, cam means for positioning the needles toward and away from the press edge, a regulator cam, connections controlled by said regulator cam for positioning the needles toward the press for said yarn sinking operation, a second cam, and a cam follower acting when rendered operative to impart an abnormally wide movement to the needles away from the press, and means for breaking said regulator cam connections and thereby to render said second cam operative to control the needle movements.
17. In a flat full-fashioned knitting machine, the combination with a series of spring beard needles and a series of instrumentalities arranged to engage and support fabric loops thereon out of contact with the needles, means for sinking yarn around the needle shanks, means for imparting vertical movements to the needles, means for imparting lateral movements to the needles toward and away from the press edge, a mechanism acting when rendered operative for moving said needles relatively toward the press to produce a loose stitch, a pattern chain, a bump on said chain, a lever controlled by engagement with said bump to engage said loose stitch mechanism, a second lever arranged for engagement with said bump, and mechanism thrown into operation by the operation of said second lever simultaneously with the operation of said loose stitch mechanism for actuating said instrumentalities.
18. In a flat full-fashioned knitting machine, the combination of a series of spring beard needles, pressing surfaces, sinkers for measuring yarn against the needle shanks, means for imparting vertical movements to the needles to draw down loops, means for imparting lateral movements to the needles toward and away from the press, a mechanism acting when rendered operative for moving said needles toward the press to produce a loose stitch, a welt turning mechanism comprising loop transfer elements, and means acting when rendered operative to cause said elements to engage with and receive initial loops of the welt portion of the fabric from the needles, a pattern chain, and a single bump on said chain acting when rendered operative to simultaneously throw into operation said welt turning and said loose stitch mechanisms.
19. In a flat full-fashioned knitting machine, the combination with a series of needles and their cooperating knitting elements, of a narrowing mechanism including means to release the take-up tension, welt turning mechanism including a series of loop taking elements arranged to take initial loops of the welt portion of the fabric, means for moving said elements to position the previously formed loops to the backs of the needles, a welt wire, means for tensioning said welt wire to tension the folded welt portion of the fabric, means for supporting said welt wire on the machine in inoperative position, and means rendered operative by the operation of said narrowing mechanism to cause said welt wire to engage with and tension the welt portion of the fabric.
20. The method of producing knitted fabric on a flat full-fashioned knitting machine which comprises traversing a carrier from one side of the machine to the other independently to lay yarn before the machine is started, thereafter operating the machine to sink the yarn about the needle shanks, during and immediately following the yarn sinking operation causing a series of loop transfer instrumentalities to be moved between the sinkers and between the needles and press surfaces to remove from the needle shanks selected kinks of yarn to form a setting-up course, relatively moving needles and instrumentalities to position the selected kinks beyond the back line of the needles, and thereafter during subsequent knitting, tensioning said kinks to the backs of the needles.
21. The method of producing knitted fabric on a flat full-fashioned knitting machine which comprises traversing a carrier from one side of the machine to the other independently to lay yarn with the machine remaining in starting position, thereafter operating the machine to sink the yarn about the needle shanks, during and immediately following said yarn sinking operation to cause a series of welt hook instrumentalities to be moved between the sinkers and between the needles and press surfaces to engage with the shanks of selected needles and with needle wale kinks of yarn held thereon, thereafter imparting to the needles an abnormal movement away from the press to disengage the needle shanks from the hooks, and thereafter to tension said instrumentalities to the backs of the needles.
22. The method of producing knitted fabric on a flat full-fashioned knitting machine which comprises operating the machine to sink yarn about the needle shanks, during and immediately following said yarn sinking operation, causing a series of loop transfer hooks to be depressed vertically between the sinkers and between the needles and press surfaces to engage with the shanks of selected needles and with needle wale kinks of yarn held thereon, moving said needles downwardly to their knockover position, imparting relative lateral movements to the needles and hooks to disengage the hooks from the needles prior to the passage of the needle eye past the hooks, and thereafter tensioning the hooks to the backs of the needles.
23. The method of producing knitted fabric on a flat full-fashioned knitting machine which comprises traversing a carrier from one side of the machine to the other independently to lay yarn with the machine remaining in starting position, thereafter operating the machine to sink the yarn about the needle shanks, during and immediately following said yarn sinking operation

to cause a series of bifurcated welt hook instrumentalities to be moved between the sinkers and between the needles and press surfaces to engage with the shanks of selected needles and with needle wale kinks of yarn held thereon, thereafter imparting to the needles an abnormal movement away from the press to disengage the needle shanks from the hooks, and thereafter during subsequent knitting to tension said instrumentalities to the backs of the needles, introducing a welt wire to tension the fabric beneath and beyond said hooks, introducing said hooks between the sinkers, and thereafter advancing the needles between the cheeks of said bifurcated hooks to take the loops from the hooks.

24. The method of producing knitted fabric on a flat full-fashioned knitting machine which comprises traversing a carrier from one side of the machine to the other independently to lay yarn with the machine remaining in starting position, thereafter operating the machine to sink the yarn about the needle shanks, during and immediately following said yarn sinking operation to cause a series of bifurcated welt hook instrumentalities to be moved between the sinkers and between the needles and press surfaces to engage with the shanks of selected needles and with needle wale kinks of yarn held thereon, thereafter imparting to the needles an abnormal movement away from the press to disengage the needle shanks from the hooks, and thereafter during subsequent knitting to tension said instrumentalities to the backs of the needles, introducing a welt wire to tension the fabric beneath and beyond said hooks, raising and advancing the hooks laterally between the sinkers above the previously knitted fabric, lowering the hooks between the knockover bits, and thereafter advancing the needles between the cheeks of said bifurcated hooks to take the loops from the hooks.

25. In a multiple section flat full-fashioned knitting machine, the combination with a series of needles and co-operating knitting elements for each section of the machine of a welt turning mechanism for taking and returning the initial loops of the welt portion of the fabric to the needles, fabric tensioning devices including a welt wire for each section, means for supporting each of said welt wires on the machine, and means for throwing said devices into operation simultaneously to tension the fabric.

26. The method of forming the set-up of fabric on a flat full-fashioned knitting machine having spring bearded needles movable en masse and cooperating sinker elements operating between the needles, and on a fabric take-up bar having a series of hook members spaced to cooperate with alternate needles to remove therefrom needle wale kinks of yarn, which comprises the steps of actuating said sinkers to kink yarn against the needles, manipulating said bar to cause said hooks acting in cooperation with the needles to engage with and cast off from below and over the boards of alternate needles their bights of yarn while the yarn is retained in a fully kinked position over the extended sinkers, moving the needles to position the yarn kinks held on the intermediate needles in the needle hooks, and thereafter moving said take-up hooks and bights held thereon to the backs of the needles.

27. The method of forming the set-up of fabric on a flat full-fashioned knitting machine having needles movable en masse, comprising the steps of kinking a first course of yarn against the needles, introducing a fabric take-up bar having loop

taking instrumentalities spaced to cooperate with alternate needles, manipulating said bar and the needles relatively thereto to cause said instrumentalities acting in cooperation with the needles to cast off from below and over the beards of alternate needles, and to position on said instrumentalities the bights of yarn formed against said alternate needles and thereafter moving said instrumentalities and bights held thereon to the backs of the needles.

28. The method of forming the set-up of fabric on a flat knitting machine having needles movable en masse and cooperating sinker elements operating between the needles, and on a fabric take-up bar having a series of hook members spaced to cooperate with alternate needles, comprising the steps of actuating said sinkers to kink yarn against the needles, manipulating said bar to position the take-up hooks between the sinkers to the hook side of the needles with the shank portions of said hooks held in a substantially vertical position and with the hook portions thereof facing forwardly for engagement with the needle shanks, manipulating said bar to engage with and remove from alternate needles their needle wale kinks of yarn, and thereafter moving said take-up hooks upwardly and forwardly to carry the hooks and yarn kinks held thereon over and to the backs of the needles.

29. The method of forming the set-up of fabric on a flat knitting machine having needles movable en masse and cooperating sinker elements operating between the needles, and on a fabric take-up bar having a series of hook members spaced to cooperate with alternate needles, comprising the steps of actuating said sinkers to kink yarn against the needles, manipulating said bar to position the take-up hooks between the sinkers to the hook side of the needles with the shank portions of said hooks in a substantially vertical position and with the hook portions thereof facing forwardly for engagement with the needle shanks, manipulating said bar to engage with and remove from alternate needles their needle wale kinks of yarn, thereafter moving said take-up hooks upwardly and forwardly to carry the hooks and yarn kinks held thereon over and to the backs of the needles, and thereafter applying a take-up tension to said bar to take up subsequently knitted fabric courses.

30. The method of forming the set-up of fabric on a flat knitting machine having needles movable en masse and cooperating sinker elements operating between the needles, and on a fabric take-up bar having a series of hook members spaced to cooperate with alternate needles, comprising the steps of actuating said sinkers to kink yarn against the needles, manipulating said bar to position the take-up hooks between the sinkers to the hook side of the needles with the shank portions of said hooks in a substantially vertical position and with the hook portions thereof facing forwardly for engagement with the needle shanks, manipulating said bar to engage with and remove from alternate needles their needle wale kinks of yarn with the yarn held in a flat kinked position over the extended sinkers, moving the needles forwardly to disengage the needles from the take-up hooks, and thereafter moving the take-up hooks upwardly and the needles rearwardly and down to form a yarn set-up on the take-up hooks and on intermediate needles.

31. The method of forming the set-up of fabric on a flat knitting machine having needles movable en masse and cooperating sinker elements

- operating between the needles, and on a fabric take-up bar having a series of hook members spaced to cooperate with alternate needles, comprising the steps of actuating said sinkers to kink 5 yarn against the needles, manipulating said bar to position the take-up hooks between the sinkers to the hook side of the needles with the shank portions of said hooks in a substantially vertical position and with the hook portions thereof facing forwardly for engagement with the needle shanks, manipulating said bar to engage with and remove from alternate needles their needle wale kinks of yarn, thereafter moving said take-up hooks upwardly and forwardly to carry the 10 hooks and yarn kinks held thereon over and to the backs of the needles, thereafter applying a take-up tension to said bar to take up subsequently knitted fabric courses, introducing and tensioning the welt wire against the fabric to take 15 up additionally knitted fabric, and thereafter moving the hooks of the take-up bar again between the knockovers and to the hook side of the needles with the needles in substantially the knockover position to cause the needles during 20 their subsequent rising movement to receive the loops held on the take-up hooks.
32. The method of forming the set-up of fabric on a flat knitting machine having needles movable en masse and cooperating sinker elements 30 operating between the needles, and on a fabric take-up bar having a series of hook members spaced to cooperate with alternate needles, comprising the steps of actuating said sinkers to kink 35 yarn against the needles, manipulating said bar to position the take-up hooks between the sinkers to the hook side of the needles with the shank portions of said hooks in a substantially vertical position and with the hook portions thereof facing forwardly for engagement with the 40 needle shanks, manipulating said bar to engage with and remove from alternate needles their needle wale kinks of yarn, thereafter moving said take-up hooks upwardly and forwardly to carry the hooks and yarn kinks held thereon 45 over and to the backs of the needles, thereafter applying a take-up tension to said bar to take up subsequently knitted fabric courses, introducing and tensioning welt wire against the fabric to take 50 up additionally knitted fabric, thereafter moving the hooks of the take-up bar again between the knockovers and to the hook side of the needles with the needles in the substantially knockover position to cause the needles during 55 their subsequent rising movement to receive the loops held on the take-up hooks, and moving the take-up bar downwardly and relatively away from the hook side of the needles to free the loops therefrom and the raising of the hook bar clear of the machine.
- 60 33. In a flat knitting machine, the combination with a series of needles and yarn sinking devices for measuring kinks of yarn about the needle shanks, of a series of fabric set-up hook elements spaced for insertion between adjacent sinkers to 65 cooperate with alternate needles, means for moving said elements relatively to the needles between adjacent sinkers and to the hook sides of the needles to engage on said hook elements the needle wale kinks of alternate needles to form a fabric set-up between said elements and intermediate needles, means for moving said elements out of the path of needle movement to maintain the setting-up course on said elements during 70 the knitting of the entire welt portion of the fabric, and means for thereafter relatively mov-

ing said elements and needles to return the setting-up course of loops to the needles.

34. In a flat knitting machine, the combination with a series of needles movable en masse and 5 yarn sinking elements operating between the needles, of means for relatively moving said elements and needles to sink yarn against the needles, a fabric take-up bar comprising a series of hook members arranged for insertion between said elements to the hook sides of the needles to engage on said hook members the needle wale kinks of selected needles, and means for positioning the hook members to the backs of the needles to take up subsequently knitted fabric courses.

35. In a flat knitting machine, the combination 15 with a series of needles movable en masse and yarn sinking elements operating between the needles, of means for relatively moving said elements and needles to sink yarn against all needles, a fabric take-up bar comprising a series 20 of hook members spaced to cooperate with alternate needles and having substantially vertical shank portions, means for advancing the sinkers to sink yarn against the shanks of the needles, means for moving said hook members downward- 25 ly between the elements to the hook sides of the needles to engage on said hook members the needle wale kinks of selected needles, and means for thereafter positioning the hook members to the backs of the needles to take up subsequently 30 knitted fabric courses.

36. In a flat knitting machine, the combination with a series of needles movable en masse and 35 yarn sinking elements operating between the needles, a fabric take-up bar comprising a series 40 of hook members spaced to cooperate with alternate needles and having substantially vertical shank portions, means for advancing the sinkers to sink yarn against the shanks of the needles, means for moving said hook members downward- 45 ly between the sinkers to the hook sides of the needles to engage on said hook members the needle wale kinks of selected needles, means for moving the needles forwardly to disengage the needles from the hook members and needle yarn 50 kinks held thereon, means for thereafter imparting relative vertical movements to needles and hook members away from each other to produce a set-up of the yarn on said hooks and on intermediate needles, and means for positioning the hook members to the backs of the needles to take up subsequently knitted courses.

37. In a flat knitting machine, the combination with a series of needles movable en masse and 55 yarn sinking elements operating between the needles, a fabric take-up bar comprising a series 60 of hook members spaced to cooperate with alternate needles and having substantially vertical shank portions, means for advancing the sinkers to sink yarn against the shanks of the needles, means for moving said hook members downward- 65 ly between the sinkers to the hook sides of the needles to engage on said hook members the needle wale kinks of selected needles, means for moving the needles forwardly to disengage the 70 needles from the hook members and needle yarn kinks held thereon and prior to the retracting movement of the sinkers, means for raising the hook members over the needles, means for moving the needles rearwardly and down to engage the yarn in the hooks to intermediate needles, and means for thereafter positioning the hook members to the backs of the needles to take up subsequently knitted courses.

38. In a flat knitting machine, the combination 75

with a series of needles movable en masse and 5
yarn sinking elements operating between the
needles, a fabric take-up bar comprising a series
of hook members spaced to cooperate with alter-
nate needles and having substantially vertical
shank portions, means for advancing the sinkers
to sink yarn against the shanks of the needles,
means for moving said hook members downward-
ly between the sinkers to the hook sides of the
needles to engage on said hook members the
needle wale kinks of selected needles, means for
moving the needles forwardly to disengage the
needles from the hook members and needle yarn
kinks held thereon, means for relatively moving
the hook members and needles to position the
hook members above the needles, means for mov-
ing the needles rearwardly and down to engage
the yarn in the hooks to intermediate needles,
means for positioning the hook members to the
backs of the needles to take up subsequently
knitted courses, and means for thereafter retract-
ing the sinkers and moving the needles forward-
ly and down to the knockover level to complete
the setting-up course upon the hook members
25 and intermediate needles.

39. In a flat knitting machine, the combination
with a series of needles movable en masse and
yarn sinking and knockover elements operating
between the needles, of means for actuating said
30 elements to sink yarn against the shanks of all
the needles, a fabric take-up bar comprising a
series of hook members spaced to cooperate with
alternate needles and having substantially verti-
cal shank portions, a resilient supporting means
35 for said bar, means for advancing the sinkers to
sink yarn against the shanks of the needles,
means for actuating said support to move the
hook members downwardly between the sinkers
to the hook sides of the needles to engage on said
40 hook members the needle wale kinks of selected
needles, means for moving the needles forwardly
away from the hook members and needle wale
kinks held thereon, means for thereafter relative-
ly moving the needles and hook members vertical-
45 ly away from each other to form a set-up on the
hook members and intermediate needles, means
for tensioning the hook members toward the
backs of the needles, and means for subsequently
moving the needles to their knockover position
50 to tension the kinked yarn vertically between the
needles and resiliently supported hooks.

40. In a flat full-fashioned knitting machine,
the combination with a series of needles movable
en masse and yarn sinking and knockover elements
55 operating between the needles, of a fabric take-up
bar comprising a series of hook members spaced
to cooperate with alternate needles and having
substantially vertical shank portions, means for
advancing the sinkers to sink yarn against the
shanks of the needles, means for moving said hook
60 members downwardly between the elements to the
hook sides of the needles to engage on said hook
members the needle wale kinks of selected needles,
means for thereafter tensioning the hook mem-
bers to the backs of the needles to take up subse-
65 quently knitted fabric courses, and means acting
prior to the advance of the sinkers in the forma-
tion of the second knitted course to move the hook
members downwardly into guiding relation be-
70 tween adjacent knockover elements.

41. In a flat knitting machine, the combination
with a series of spring bearded needles movable
en masse with relation to a press edge and yarn
sinking and knockover elements operating be-
75 tween the needles, of a welt bar comprising a

series of hook members spaced to cooperate with
alternate needles to receive an initial course of
welt fabric, each of said hook members having a
substantially vertical shank portion and a hook
5 formed on the front side thereof provided with a
needle guiding recess, means for imparting rela-
tive movements to said hook members and needles
to return the initial course of loops to the needles
comprising means acting when rendered operative
10 to move said hook members rearwardly to the
hook side of the needles with the needles in sub-
stantially their knockover position and with the
bottom portions of said hooks at a level above the
knockover bits and previously knitted fabric,
means for depressing the hooks between the
15 knockover bits to position the loops held thereon
below the sinker level prior to the advancing
movement of the sinkers, means for advancing the
sinkers over the welt fabric held on the welt hooks,
means for engaging the welt hooks against the
20 press edge to cause the guiding surfaces formed
thereon to be engaged by the rising needles to
guide the needles into the loops held on the welt
hooks, means acting thereafter for depressing said
hooks to disengage the loops held thereon, and
25 means for lifting said welt hooks clear of the ma-
chine.

42. In a flat full-fashioned knitting machine,
the combination with a series of needles movable
as a unit and cooperating knitting elements oper-
30 ating between the needles, of means for forming a
set-up of new fabric on said needles comprising a
fabric set-up bar having hooks arranged for in-
sertion between said cooperating elements to en-
gage on said set-up hooks an initial course of
35 yarn, said set-up hooks having formed thereon
cammed guiding surfaces to guide the hooks be-
tween the elements, and portions adjacent to said
surfaces of a width substantially equal to the
spacing between the elements to maintain the
40 hooks in a centered position between the elements.

43. In a flat full-fashioned knitting machine,
the combination with a series of needles movable
as a unit and cooperating knitting elements oper-
45 ating between the needles, of means for forming a
set-up of new fabric on said needles comprising a
fabric set-up bar having hooks spaced at twice
the needle index and arranged for insertion be-
tween said cooperating elements to the hook side
50 of the needles to engage on the set-up hooks an
initial course of yarn, said set-up hooks having
formed thereon cammed guiding surfaces to guide
said hooks between the elements, and portions
adjacent to said surfaces of a width substantially
55 equal to the spacing between the elements to
maintain the hooks in a centered position be-
tween the elements.

44. In a flat full-fashioned knitting machine,
the combination with a series of needles movable
as a unit and cooperating knitting elements oper-
60 ating between the needles, of a welt turning
mechanism comprising welt transfer members
arranged to return the initial course of loops held
thereon to the needles, said transfer elements
having formed thereon cammed guiding surfaces
65 to guide said members between the elements, and
portions adjacent to said surfaces of a width sub-
stantially equal to the spacing between the ele-
ments to maintain the transfer members in a
centered position between the elements prior to
70 and during the transfer.

45. In a flat full-fashioned knitting machine,
the combination with a series of needles movable
as a unit and cooperating knitting elements oper-
75 ating between the needles, of a welt turning

- mechanism comprising a welt bar having hooks spaced at twice the needle index and arranged for insertion between said elements to the hook side of the needles to engage on said hooks an initial course of yarn, and again at the end of the welt turning operation to return the loops held on said hooks to the needles, said welt hooks having formed thereon cam guiding surfaces to guide said hooks between the elements both during the taking and again during the returning of the initial loops of the needles, and portions adjacent to said surfaces of a width substantially equal to the spacing between the elements to maintain the hooks in a centered position between the elements.

46. In a flat full-fashioned knitting machine, the combination with a series of spring bearded needles movable en masse and cooperating knitting elements including yarn measuring sinkers, of means for forming a set-up of new fabric on said needles comprising a fabric set-up bar having hooks spaced to cooperate with alternate needles, means for relatively moving the needles and sinkers to sink yarn against the needles, and means for relatively moving the hooks and needles to cause the hooks acting in cooperation with the needles to cast off from below and over the needle beards and to position in said hooks the needle wale kinks of alternate needles to form a fabric set-up on said hooks and on the intermediate needles.

47. In a flat full-fashioned knitting machine, the combination with a series of spring bearded needles movable en masse and cooperating knitting elements including yarn measuring sinkers, of means for forming a set-up of new fabric on said needles comprising a fabric set-up bar having hooks spaced to cooperate with alternate needles, means for relatively moving the needles and sinkers to sink yarn against the needles, and means for relatively moving the hooks and needles to cause the hooks acting in cooperation with the needles to cast off from below and over the needle beards and to position in said hooks the needle wale kinks of alternate needles to form a fabric set-up on said hooks and on the intermediate needles, means for maintaining said hooks and loops held thereon out of the path of needle movement during the subsequent knitting of the welt portion of the fabric, and means for relatively moving the hooks and needles to return the loops to the needles to complete the forming of the welt.

48. In a flat knitting machine, the combination with a series of needles and their cooperating knitting elements including yarn measuring sinkers, of a series of fabric loop engaging implements spaced to cooperate with selected needles to cast off needle wale loops from the needles and to position said loops on the implements beyond the back line of the needles during subsequent knitting, and thereafter to return the loops to the needles, means for imparting relative movements to the needles and implements to cast off from the needles and to position the needle wale loops of selected needles on said implements beyond the back line of the needles, means acting thereafter to cause the said implements to follow the forward and back movements of the needles during the subsequent knitting, and means for thereafter imparting relative movements to the needles and the implements to return loops to the needles.

49. In a flat full-fashioned knitting machine, the combination with a series of spring bearded needles and their cooperating knitting elements including yarn measuring sinkers, of a series of fabric loop engaging implements spaced to cooperate with selected needles to cast off needle wale loops from the needles and to position said loops on the implements beyond the back line of the needles during subsequent knitting, and thereafter to return the loops to the needles, means for imparting relative movements to the needles and implements to cast off from the needles and to position the needle wale loops of selected needles on said implements beyond the back line of the needles, means for thereafter causing the said implements to follow the forward and back movements of the needles during the subsequent knitting, and means for thereafter imparting relative movements to the needles and the implements to return loops to the needles.

50. In a flat full-fashioned knitting machine, the combination with a series of needles and means for sinking yarn about the needle shanks, of a welt turning mechanism comprising a series of loop transfer elements adapted to receive and to return initial loops of the welt portion of the fabric to the needles, a hanging frame on which said elements are supported, and a pivotal support for said frame located at a point above the point of operation of said elements to permit said elements to move freely toward and away from the needles.

51. In a flat full-fashioned knitting machine, the combination with a series of needles and means for sinking yarn about the needle shanks, of a welt turning mechanism comprising a series of loop transfer elements adapted to receive and to return initial loops of the welt portion of the fabric to the needles, a hanging frame on which said elements are supported, a pivotal support for said frame located at a point substantially vertically above the point of operation of said elements to permit said elements to move freely toward and away from the needles, and a resilient fabric take-up tension acting on said frame.

52. In a flat full-fashioned knitting machine, the combination with a series of needles and means for sinking yarn about the needle shanks, of a welt turning mechanism comprising a series of loop transfer elements adapted to receive and to return initial loops of the welt portion of the fabric to the needles, a hanging frame on which said elements are supported, a vertically movable pivotal support on which said frame is mounted to swing to permit movement of said elements freely toward and away from the needles, means for imparting lateral and vertical movements to said frame and elements supported thereon to engage an initial course of loops of the welt portion of the fabric with said elements, and means for swinging said frame away from the needles to take-up subsequently knitted fabric.

53. In a flat full-fashioned knitting machine, the combination with a series of needles movable as a unit, and means for sinking yarn about the needle shanks, of a welt turning mechanism comprising a series of loop transfer elements adapted to receive and return the initial loops of the welt portion of the fabric to the needles, a hanging frame on which said elements are supported to move freely toward and away from the needles, a vertically movable pivotal support for said frame, connections including actuating cams to control said lateral and vertical movements of the

ments with relation to the needles, and cams for controlling the operation of said connections.

54. In a flat full-fashioned knitting machine, the combination with a series of needles movable as a unit, and means for sinking yarn about the needle shanks, of a series of loop transfer elements, a hanging frame on which said elements are mounted, a vertically movable pivotal support for said frame, means for imparting vertical movements to said pivotal support, means for imparting swinging movements to said frame, and mechanism for actuating each of said means in timed relation to engage an initial course of loops of the welt portion of the fabric with said loop transfer elements, and thereafter to return said loops to the needles to complete the turning of the welt.

55. In a flat full-fashioned knitting machine, the combination with a series of needles movable as a unit, and means for sinking yarn about the needle shanks, of a welt turning mechanism comprising a series of loop transfer elements adapted to receive and return the initial loops of the welt portion of the fabric to the needles, a hanging frame on which said elements are supported to move freely toward and away from the needles, a vertically movable pivotal support for said frame, connections including actuating cams to control said lateral and vertical movements of the elements with relation to the needles, cams for controlling the operation of said connections, and a timing mechanism for rendering said cams operative to cause the loop transfer elements to receive and thereafter to return the initial loops of the welt portion of the fabric to the needles.

56. In a flat full-fashioned knitting machine, the combination with a series of needles movable as a unit and cooperating knitting elements operating between the needles, of a welt turning mechanism comprising a welt bar, a series of vertical welt hooks mounted thereon arranged for insertion between said elements to the hook side of the needles to receive and return an initial course of the welt fabric to the needles, a hanging frame on which said bar is supported, a vertically movable pivotal support for said frame, cam mechanism for imparting vertical movements to said pivotal support and horizontal swinging movements to said frame to engage the hooks with the initial course of the welt fabric, and thereafter to return the loops held thereon to the needles, a fabric tension acting on said frame to tension the hooks and fabric supported thereon to the backs of the needles, means to disconnect the swinging frame from the horizontal swing mechanism to permit the operation of the take-up, means for arresting the continued swinging movement of the frame under the influence of the take-up tension in a predetermined position, and means acting automatically at the completion of the welt fabric to operatively connect the frame to the horizontal swing mechanism.

57. In a flat full-fashioned knitting machine, the combination with a series of needles movable as a unit, and means for sinking yarn about the needle shanks, of a series of loop transfer elements, a hanging frame on which said elements are mounted, a vertically movable pivotal support for said frame, means for imparting lateral and vertical movements to said frame and elements supported thereon to engage an initial course of loops of the welt portion of the fabric with said loop transfer elements, and thereafter to return said loops to the needles to complete the turning of the welt, means for controlling

the swinging movement of the frame to maintain said transfer elements in an idle position to the back side of the needles, and means for disconnecting the frame therefrom to permit the frame to be swung clear of the machine.

5

58. In a flat full-fashioned knitting machine, the combination with a series of needles and means for sinking yarn about the needle shanks, of a fabric set-up mechanism comprising a set-up bar, a series of hooks mounted thereon to engage with and maintain thereon a setting-up course of loops, a hanging frame on which said bar is supported to permit a limited movement of the bar lengthwise of the machine, a vertically movable pivotal support for said frame, means for imparting vertical movements to said pivot and swinging movements to said frame and elements supported thereon to engage an initial course of set-up loops on said hooks, and guiding means arranged to engage said bar to register said hooks in a predetermined operating relationship with relation to the needles and cooperating elements lengthwise of the machine.

59. In a flat full-fashioned knitting machine, the combination with a series of needles movable as a unit, a press edge cooperating therewith, and sinker and knockover elements operating between the needles, of a fabric set-up mechanism comprising a fabric set-up bar, a series of hooks mounted thereon having vertical shank portions and hooks arranged to engage needle wale kinks of alternate needles to the hook side of the needles, a hanging frame on which said set-up bar is mounted for a limited movement lengthwise of the machine, a vertically movable pivotal support for the frame, means for imparting vertical movements to the pivot and swinging movements to the frame to position the hooks between the sinkers to the hook side of the needles to take needle wale kinks from alternate needles, a guide cam arranged for engagement with said bar to guide the hooks between the sinkers and having a cutaway portion to permit a free adjustment of the hooks when positioned between the sinkers lengthwise of the machine through contact with the sinkers.

60. In a flat full-fashioned knitting machine, the combination with a series of needles movable as a unit, a press edge cooperating therewith, and sinker and knockover elements operating between the needles, of a fabric set-up mechanism comprising a fabric set-up bar, a series of hooks mounted thereon having vertical shank portions and hooks arranged to engage needle wale kinks of alternate needles to the hook side of the needles, a hanging frame on which said set-up bar is mounted for a limited movement lengthwise of the machine, a vertically movable pivotal support for the frame, means for imparting vertical movements to the pivot and swinging movements to the frame to engage on the hooks an initial course of needle wale kinks from alternate needles, and thereafter to move said hooks to the backs of the needles, means for controlling the vertical movements of said pivotal support and swinging movements of the frame to move the hooks over the needles in their knockover position and between the knockover elements to the hook side of the needles for returning the initial course of loops thereto, and a guide cam for engaging the bar to guide the hooks between the knockover elements having formed thereon a cutaway portion to permit a free adjustment of the hooks when positioned between the knockover

- elements lengthwise of the machine through knockover bit and sinker contact.
61. In a flat full-fashioned knitting machine, the combination with a series of needles movable as a unit, a press edge cooperating therewith, and sinker and knockover elements operating between the needles, of a fabric set-up mechanism comprising a fabric set-up bar, a series of hooks mounted thereon having vertical shank portions and hooks arranged to engage needle wale kinks of alternate needles to the hook side of the needles, a hanging frame on which said set-up bar is mounted, a vertically movable pivotal support for the frame including cams and cam followers, connections for controlling the vertical movements of the pivotal support and swinging movements of the frame to position the hook elements between the sinkers to the hook side of the needles, and spring means for maintaining said followers in engagement with their cams, said frame swing control cam being shaped to permit the engagement of the hooks when positioned between the sinkers yieldingly against the press edge under the influence of said spring.
62. In a flat full-fashioned knitting machine, the combination with a series of needles and their cooperating knitting elements, of a welt turning mechanism including a series of loop taking elements arranged to receive an initial course of loops of the welt portion of the fabric, means for moving said elements to carry the previously formed loops to the backs of the needles, a welt wire, a fabric take-up acting on said wire, means for supporting the wire on the machine in inoperative position against said tension, and means acting when rendered operative to release said wire to engage the wire with and tension the fabric.
63. In a flat full-fashioned knitting machine, the combination with a series of needles and their cooperating knitting elements, of a welt turning mechanism including a series of loop taking elements arranged to receive an initial course of loops of the welt portion of the fabric, tensioning means acting on said elements to tension the elements during the knitting of only a portion of the welt fabric, a welt wire, a fabric take-up acting on said wire, means for supporting the wire on the machine in inoperative position against said tension, and means for automatically releasing said wire to engage the wire with and tension the fabric during the knitting of subsequent welt courses of fabric.
64. In a flat full-fashioned knitting machine, the combination of a series of spring beard needles, pressing surfaces, sinkers for measuring yarn against the needle shanks, means for imparting vertical movements to the needles to draw down loops, means for imparting lateral movements to the needles toward and away from the press, means for producing relative motion between the needles and sinkers to form a loose course, mechanism for setting up a new fabric on the needles comprising a series of loop engaging elements, means acting when rendered operative to cause said elements to receive and to maintain thereon an initial setting-up course of loops of the welt portion of the fabric, and pattern mechanism for automatically rendering said setting-up mechanism and loose stitch mechanism operative simultaneously.
65. In a multiple section flat full-fashioned knitting machine, the combination with each series of needles and their cooperating knitting
- elements, of a welt turning mechanism including a series of loop taking elements arranged to receive and hold thereon an initial course of loops of the welt portions of the fabric, a welt wire for each section, means for tensioning each of said welt wires to tension the welt portions of the fabrics, means for supporting each of said welt wires on the machine in inoperative position, and means for simultaneously releasing said welt wires to engage the welt wires with and tension the fabrics on their respective sections.
66. In a multiple section flat full-fashioned knitting machine, the combination with a series of needles and cooperating knitting elements for each section of the machine, of a welt turning mechanism comprising a series of loop transfer hooks cooperating with each section adapted to receive and return the initial loops of the welt portion of the fabric to the needles, a welt bar on which said hooks are carried, means for imparting movements simultaneously to each of said welt bars and hooks mounted thereon to deposit in said hooks and to return an initial course of loops to the needles, and guiding means to engage and guide each of said bars for separately locating each bar longitudinally of the needle series to accurately align said hook elements with the needles to take and to return the loops thereto.
67. In a multiple section flat full-fashioned knitting machine, the combination with a series of needles and cooperating sinker elements for each section of the machine, of mechanism for setting up new fabric on each section of the machine comprising for each section a bar and a series of set-up hooks spaced to cooperate with alternate needles and arranged for insertion between the sinkers to the hook sides of the needles to engage the yarn of an initial course, means for actuating the sinkers on each section simultaneously to kink yarn about all the needle shanks for the formation of a setting-up course of fabric, means for simultaneously actuating said bars to engage the yarn of the initial course, and guiding means to engage and guide each of said bars for separately locating each bar longitudinally of the needle series to accurately align the hooks with the needles.
68. In a flat full-fashioned knitting machine, the combination with a series of needles movable as a unit and cooperating knitting elements, of a main cam shaft, operating connections controlled therefrom for operating the needles and cooperating elements, a series of loop engaging implements arranged to receive thereon loops of a fabric course, and thereafter to return said loops to the needles, supporting means for said elements supported on the machine above the needle bed, and actuating connections therefor comprising a supplemental cam shaft located adjacent said element support, means for driving the supplemental cam shaft in timed relation to the main cam shaft, cams on the supplemental cam shaft and cam follower connections for actuating the loop engaging elements in timed relation to the needle movement, and pattern means for throwing said actuating connections into and out of operation.
69. In a flat full-fashioned knitting machine, the combination with a series of needles movable as a unit and cooperating knitting elements, of a main cam shaft, operating connections controlled therefrom for operating the needles and cooperating elements, a series of loop engaging implements arranged to receive thereon loops

- of a fabric course, and thereafter to return said loops to the needles, means for supporting said elements on the machine, and actuating connections therefor comprising a supplemental cam shaft, means for driving said supplemental cam shaft in timed relation to the main cam shaft, and connections controlled from said supplemental cam shaft for imparting vertical and forward and back motions to said loop engaging elements in timed relation to the needle movement.
70. In a flat full-fashioned knitting machine, the combination with a series of needles movable as a unit and cooperating knitting elements, of a continuously rotating cam shaft, actuating connections for the machine operated from said cam shaft comprising a cam follower, a plurality of cams on the cam shaft arranged alternatively for operative engagement with said follower, and means for shifting the cam shaft and cams axially for positioning said cams alternatively in operative relationship to said follower comprising a pair of cam disks, a plurality of radially spaced face cams formed on adjacent faces of said disks, a shift roll, a shift lever on which said roll is supported for movement into alternative engagement with one or another of said face cams, and means rendered operative by the continued rotation of the cam shaft for returning said shift lever to inoperative position.
71. In a flat full-fashioned knitting machine, the combination with a series of needles movable as a unit and cooperating knitting elements, of a welt turning mechanism comprising a series of elements arranged to cooperate with the needles to receive and to return an initial course of the welt fabric to the needles, actuating connections for said elements comprising a continuously rotating cam shaft, a cam follower connected to control movement of said elements, an idler cam on the cam shaft for normally positioning said follower, separate operating cams for controlling the movement of said elements to receive and to return the loops to the needles located on opposite sides of said idler cam, and means for shifting the cam shaft axially in opposite directions from a neutral intermediate position to engage the follower alternatively with one or the other of said operating cams.
72. The method of producing knitted fabric on a flat full-fashioned knitting machine having needles movable en masse and jack and dividing sinkers, which comprises feeding yarn and advancing the jack sinkers to sink the yarn, introducing a fabric set-up bar having a series of hook members spaced to cooperate with alternate needles, manipulating said bar to position the take-up hooks between the sinkers to the hook side of the needles to engage the hook portions thereof with the floats of yarn extending between each pair of needles prior to the operation of the dividing sinkers, and manipulating said bar to lift the needle wale kinks of alternate needles over and beyond the back line of the needles.
73. In a flat knitting machine, the combination of a series of needles and their cooperating knitting elements including yarn measuring jack and dividing sinkers, of a series of fabric hooks spaced to cooperate with alternate needles and arranged to be inserted vertically between adjacent sinkers to the beard side of the needles, means for advancing the jack sinkers to kink yarn about each pair of needle shanks, and means
- for imparting relative movements to the needles and hooks to engage the hooks with the floats of yarn extending between each pair of needle shanks, means for advancing the dividing sinkers, and means for moving the hooks to position the 5 kinks of yarn held thereby beyond the back line of the needles for subsequent knitting on the needle series.
74. In a flat full-fashioned knitting machine, the combination of a series of needles and their 10 cooperating knitting elements including a series of successively actuated sinkers successively operable to sink yarn between each pair of needles, a series of hooks, means for advancing said sinkers to sink yarn about the shanks of each 15 successive pair of needles, and means for moving the hooks to engage the floats of yarn while supported by the fully advanced sinkers across the shanks of each pair of needles, and to position the hooks and kinks of yarn held thereby out of 20 the path of needle movement for subsequent knitting on the needle series.
75. In a flat full-fashioned knitting machine having a series of needles movable as a unit and yarn measuring sinkers, the combination with a 25 series of loop engaging implements spaced to cooperate with selected needles, of supporting and actuating mechanism therefor comprising a hanging frame on which said implements are mounted, a vertically movable support for said frame, 30 means for imparting vertical and swinging movements to the frame in timed relation to needle movement to engage upon said implements and to position needle wale loops of selected needles out of contact with and beyond the back line of 35 the needles, and thereby to support the needle loops out of the path of needle movement during the subsequent knitting, and means for thereafter imparting vertical and swinging movements to said frame and implements supported thereon 40 to return the loops to the needles.
76. In a flat full-fashioned knitting machine having a series of needles movable as a unit and yarn measuring sinkers, the combination with a 45 series of loop engaging implements spaced to cooperate with selected needles, of supporting and actuating mechanism therefor comprising a hanging frame on which said implements are mounted, a vertically movable pivotal support for said frame, and means for imparting vertical and 50 swinging movements to the frame and implements carried thereon in timed relation to needle movement to cast off from the needles and to position the needle wale loops of selected needles on said implements out of contact with and beyond the back line of the needles, and thereby to support the needle loops out of the path of needle movement during the subsequent knitting.
77. In a flat full-fashioned knitting machine having a series of needles movable as a unit, and 60 yarn measuring sinkers, the combination with a series of loop engaging implements spaced to cooperate with selected needles, of supporting and actuating mechanism therefor comprising a hanging frame on which said implements are 65 mounted, a vertically movable pivotal support for said frame, cam and follower connections for imparting vertical and swinging movements to the frame and implements in timed relation to the needle motions to engage on said implements 70 and to position loops of a fabric course out of contact with and beyond the back line of the needles, and means acting thereafter to render said cam and follower connections inoperative and thereby to maintain said implements and loops 75

carried thereon out of the path of the needle movement during subsequent knitting on the needle series.

78. In a multiple section flat full-fashioned knitting machine, the combination with knitting instrumentalities for each section including a series of needles movable as a unit, cooperating yarn measuring sinkers and a series of loop engagings implements arranged to receive thereon loops of a fabric course, and thereafter to return said loops to the needles, driving mechanism for said instrumentalities including a main cam shaft extending along the length of the machine, a secondary cam shaft extending along the length of the machine, means for driving said shafts in timed relation, cam and follower connections from one of said shafts for actuating certain of said above named instrumentalities, and cam and follower connections from the other of said shafts for actuating others of said above named instrumentalities.

79. In a flat full-fashioned knitting machine having a series of needles movable as a unit, yarn measuring sinkers and a fabric transfer mechanism comprising a series of loop engaging implements spaced to cooperate with selected needles to cast off the needle wale loops from the needles and to position said loops on the implements beyond the back line of the needles during subsequent knitting on the needle series, and thereafter to return the loops to the needles, a support on which said loop engaging implements are carried, actuating connections therefor including forward and back and vertical motion cams and cam followers for moving said support and loop engaging implements to engage with and position selected needle wale loops out of the path of needle movement, a separate set of forward and back and vertical motion cams for moving said support and loop engaging implements to return said loops to the needles, means for driving said cams in timed relation to the operation of the machine, and pattern mechanism for selectively throwing each of said sets of cams into and out of operation.

80. In a flat full-fashioned knitting machine having a series of needles movable as a unit, yarn measuring sinkers and a fabric transfer mechanism comprising a series of loop engaging implements spaced to cooperate with selected needles to cast off the needle wale loops from the needles and to position said loops on the implements beyond the back line of the needles during subsequent knitting on the needle series, and thereafter to return the loops to the needles, a support on which said loop engaging implements are carried, actuating connections therefor including forward and back and vertical motion cams and cam followers for moving said support and loop engaging implements to engage with and position selected needle wale loops out of the path of needle movement, a separate set of forward and back and vertical motion cams for moving said support and loop engaging implements to return said loops to the needles, and means for driving said cams in timed relation to the operation of the machine.

81. In a flat full-fashioned knitting machine, the combination with a series of needles and their cooperating knitting elements, of a welt turning mechanism comprising a carrier and a series of welt setting-up implements supported thereon, and means for moving said implements away from the needles to tension the fabric, a welt wire, means for supporting the welt wire in active posi-

tion, fabric take-up means associated with the welt wire, and means operable while said implements continue to tension the fabric to render the welt wire active to take up a fold of welt fabric.

82. In a flat full-fashioned knitting machine, the combination with a series of needles and their cooperating knitting elements, of a welt turning mechanism comprising a carrier and a series of welt setting-up implements supported thereon, means for moving said implements away from the needles to tension the fabric, a welt wire, a support on the machine independent of said carrier for supporting the welt wire during the knitting of a portion of the welt fabric in position for subsequent operation to take up the fabric, fabric take-up means associated with the welt wire, and means acting when rendered operative to cause the welt wire to take up the welt fabric.

83. In a flat full-fashioned knitting machine, the combination with a series of needles and their cooperating knitting elements, of a welt turning mechanism comprising a carrier and a series of welt setting-up implements supported thereon, and means for moving said implements away from the needles to tension the fabric, a welt wire, a support into which the welt wire can be laid prior to the time it is required, said support including means to prevent endwise movement of the welt wire in its support, fabric take-up means associated with the welt wire, and means for rendering said take-up means operative to cause said welt wire to form a fold in and to take up the welt fabric.

84. In a flat full-fashioned knitting machine, the combination with a series of needles and their cooperating knitting elements, of a welt turning mechanism comprising a carrier and a series of welt setting-up implements supported thereon, and means for moving said implements away from the needles to tension the fabric, a welt wire, means for supporting the welt wire in inoperative position, fabric take-up means associated with the welt wire, means acting when rendered operative to cause the welt wire and associated fabric take-up to take up the fabric, and means for guiding the welt wire during movement from its supported inoperative position into engagement with the fabric.

85. In a flat full-fashioned knitting machine, the combination with a series of needles and their cooperating knitting elements, of a welt turning mechanism comprising a carrier and a series of welt setting-up implements supported thereon, and means for moving said implements away from the needles to tension the fabric, a welt wire, a fabric take-up acting on said welt wire, means for supporting the wire on the machine in inoperative position against said tension, means for guiding the welt wire from its support into engagement with the fabric, means acting when rendered operative to release said welt wire from its support, and means for checking the movement of the welt wire into engagement with the fabric.

86. In a flat full-fashioned knitting machine, the combination with a series of needles and their cooperating knitting elements, of a welt turning mechanism comprising a carrier and a series of welt setting-up implements supported thereon arranged for movement away from the needles in a take-up direction, and means for moving said implements away from the needles in a take-up direction, a welt wire, means for supporting the welt wire on the machine in inoperative position and for guiding the welt wire against the fabric,
